UNITED STATES PATENT OFFICE.

EDWARD L. BRACY, OF BALTIMORE, MARYLAND, ASSIGNOR TO RICHARD H. WRIGHT,
OF DURHAM, NORTH CAROLINA.

CIGARETTE-PACKAGING MACHINE.

1,247,364.

Specification of Letters Patent. Patented Nov. 20, 1917.

Application filed September 23, 1915. Serial No. 52,258.

To all whom it may concern:

Be it known that I, EDWARD L. BRACY, a citizen of the United States, residing at Baltimore and State of Maryland, have invented new and useful Improvements in Cigarette-Packaging Machines, of which the following is a specification.

This invention relates to machines for packaging various articles in vendable condition, such for instance as cigarettes, cigars and other analogous articles. The present machine has been particularly organized for packaging cigarettes, and one object of the invention as therein embodied is to provide the feed end or preliminary inclosure or wrapper preparing and feeding mechanism of a cigarette packaging machine with instrumentalities for feeding, cutting into proper lengths and assembling the parts or elements of an inclosure or wrapper or whereby a cup and interliner may be properly associated for conjoint folding operations and have in some instances a coupon introduced and secured therein if desired, or prepare an inclosure or wrapper of plain foil, glacine, or plain paper of any character, with or without printed matter, and to position the inclosure or wrapper as thus prepared relatively to a molding means to receive a predetermined number of cigarettes, and then to unitedly press the inclosure or wrapper and cigarettes into the molding means and subsequently shape and seal or complete the package in finished form from the machine without requiring insertion of the package in a preliminarily and extraneously prepared cup inclosure, or to insert said package in a cup that is regularly fed into position to receive the package in accordance with the particular form of package that may be preferred. A further object of the invention is to provide for inclosure of cigarettes of various numbers in different forms of wrappers or inclosing means through the medium of the same essential elements of the machine with a simple substitution of replaceable expellers and change of occluding means or shields in the assembling or distributing chamber for the cigarettes to correspond to the form of the expeller that is used, and thereby increase the scope of operation and general efficiency of unitary cigarette packaging machine organizations. A further object of the invention is to provide a cigarette

packaging machine with a banding attachment that may be used as desired and in continuation with relation to the remaining mechanism, or said banding attachment may be rendered inoperative without affecting the operation of the remaining mechanism.

With these general objects and other specific objects and advantages which will be subsequently related, the invention consists in the construction of various devices and mechanisms and in the combinations and sub-combinations of said devices and mechanisms hereinafter described and claimed and by which the full organized machine is rendered practical in the attainment of the results sought.

In the drawings:

Figure 1 is a longitudinal vertical section of the feed and wrapper preparing end of the machine embodying the features of the invention and particularly showing the instrumentalities for associating the cup and interliner and depositing a coupon therein.

Fig. 2 is a view similar to Fig. 1 up to the coupon feed of the latter figure and on a larger scale, and arranged to prepare an inclosure for a package that is to be inserted in an independently prepared cup, the pasting mechanism being disposed in advance of the feed roll or reel.

Fig. 3 is an enlarged longitudinal vertical section of a portion of the feed table shown by Fig. 1.

Fig. 4 is an enlarged transverse vertical section of the feed table taken in the plane of the line 4—4, Fig. 1.

Fig. 5 is a longitudinal vertical section on an enlarged scale of a portion of the feed table as shown by Fig. 2.

Fig. 6 is a transverse vertical section on an enlarged scale taken in the plane of the line 6—6, Fig. 2.

Fig. 7 is a side elevation of the machine with the feed table as shown by Fig. 1.

Fig. 8 is a top plan view of the machine as shown by Fig. 7 and partially broken away.

Fig. 9 is a transverse vertical section taken in the plane of the line 9—9, Fig. 8, and looking in the direction of the arrows.

Fig. 9^a is a longitudinal section taken in the plane of the line 9^a—9^a of Fig. 9.

Fig. 9^b is a cross-section taken in the plane of the line 9^b—9^b of Fig. 9^a.

Fig. 10 is a top plan view, partially in

horizontal section, on an enlarged scale of the feed hopper end of the machine and a portion of the feed table and showing the hopper body removed.

5 Fig. 11 is a transverse vertical section taken in the plane of the line 11—11, Fig. 10, with the hopper body applied in operative position.

10 Fig. 12 is a sectional plan view of the hopper or cigarette assembling extremity of the machine, illustrating the cigarette assembling or distributing chamber in horizontal section and parts broken away to disclose the operating mechanism for the expellers.

15 Fig. 13 is a transverse vertical section taken in the plane of the line 13—13, Fig. 12.

20 Fig. 14 is a longitudinal vertical section taken in the plane of the line 14—14, Fig. 10, and showing part of the hopper in position and a portion of the operating mechanism removed.

25 Fig. 15 is a longitudinal vertical section taken in the plane of the line 15—15, Fig. 10.

30 Fig. 16 is a longitudinal vertical section taken in the plane of the line 16—16, Fig. 8.

35 Fig. 17 is a transverse vertical section taken in the plane of the line 17—17, Fig. 8, and looking in the direction of the arrows, a portion of the hopper and plunger mechanism being broken away.

40 Fig. 18 is an end elevation partially in cross-section and broken away with parts illustrated in section and incomplete of the hopper end of the machine and looking toward the side of the mechanism opposite that shown by Fig. 17.

45 Fig. 19 is an enlarged sectional elevation showing a portion of the mold wheel, the mechanism for expelling the packages therefrom, and the compression devices for the packages that coöperate with the expellers of the mold wheel.

50 Fig. 20 is a detail longitudinal vertical section of a portion of the compression devices as shown by Fig. 19 in a different position.

55 Fig. 21 is a horizontal section taken in the plane of the line 21—21, Fig. 20.

60 Fig. 22 is a transverse vertical section taken in the plane of the line 22—22, Fig. 19.

Fig. 23 is a detail sectional elevation of a part of the compression register mechanism.

65 Fig. 24 is a detail perspective view of a portion of the expeller for the cigarette assembling chamber and illustrating one of the fingers as reduced in vertical extent to adapt the same to expel twenty cigarettes from the chamber.

70 Fig. 25 is a detail sectional elevation of a portion of the cigarette assembling chamber showing a shield or baffle therein to correspond to the expeller illustrated by Fig. 24 and whereby an open space is

provided for compression relatively to a bunch of twenty cigarettes.

75 Fig. 26 is a detail sectional view showing the manner of compressing the bunch of cigarettes as delivered from the assembling chamber and expeller as shown arranged by Figs. 24 and 25.

Fig. 27 shows a diagrammatic view of a bunch of twenty cigarettes fully compressed or closely arranged and having rounded corners and which is the result of the arrangement of the cigarettes in the compression chamber as shown by Fig. 26.

80 Fig. 28 is a detail perspective view of a portion of an expeller of a different type adapted for discharging a bunch of cigarettes from the assembling chamber.

85 Fig. 29 is a detail sectional elevation of a portion of the assembling chamber arranged for operation with the expeller as shown by Fig. 28.

90 Fig. 30 is a detail sectional view of the compression chamber showing the arrangement of the cigarettes therein as discharged from the assembling chamber illustrated by Fig. 29 by the expeller shown by Fig. 28.

95 Fig. 31 is a diagrammatic view of the bunch of twenty cigarettes as compressed in accordance with the disposition thereof in the compression chamber shown by Fig. 30.

100 Fig. 32 is a detail perspective view of a portion of an expeller adapted for discharging a bunch of ten cigarettes from the assembling chamber.

105 Fig. 33 is a sectional elevation of a portion of the assembling chamber with which the expeller shown by Fig. 32 coöperates.

Fig. 34 is a detail sectional view showing the compression chamber which receives the bunch of ten cigarettes as discharged from the assembling chamber illustrated by Fig. 33.

110 Fig. 35 is a diagrammatic view showing the bunch of ten cigarettes as compressed in accordance with the disposition of the cigarettes in the compression chamber shown by Fig. 34.

115 Fig. 36 is a detail perspective view showing the arrangement of the expeller for discharging a bunch of ten cigarettes in another form.

Fig. 37 is a sectional elevation of a portion of the assembling chamber showing the arrangement of the cigarettes for discharge by the expeller illustrated by Fig. 36.

120 Fig. 38 is a detail sectional view of the compression chamber showing the manner in which the cigarettes are disposed therein when discharged from the chamber shown by Fig. 37 through the operation of the expeller illustrated by Fig. 36.

125 Fig. 39 is a diagrammatic view showing the bunch of ten cigarettes as compressed by the chamber illustrated by Fig. 38.

Fig. 40 is a detail perspective view of a portion of the expeller showing the parts thereof arranged to discharge twelve cigarettes from the assembling chamber.

- 5 Fig. 41 is a detail sectional elevation of a portion of the assembling chamber showing the arrangement of the twelve cigarettes therein for discharge by the expeller illustrated by Fig. 40.
- 10 Fig. 42 is a detail sectional view of the compression chamber showing the arrangement of twelve cigarettes as discharged and delivered from the chamber shown by Fig. 41 through the operation of the expeller 15 illustrated by Fig. 40.

Fig. 43 is a diagrammatic view showing the bunch of twelve cigarettes as compressed in the chamber illustrated by Fig. 42.

Figs. 44, 45, 46 and 47 illustrate the steps 20 of folding a combined cup and interliner around a bunch of cigarettes which are illustrated as twenty in number and wherein a coupon may also be deposited if desired.

Fig. 48 is a plan view illustrating the preliminary arrangement of the parts of the cup and interliner as fed forward to receive the bunch of cigarettes to be inclosed 25 thereby.

Figs. 49, 50, 51 and 52 illustrate the steps 30 in inclosing a bunch of cigarettes, shown as twenty in number, in plain foil, glaccine, or plain paper of any suitable character with or without printed matter for insertion in an independently prepared cup.

35 Fig. 53 is a detail perspective view of the cup adapted to receive the package as shown completed by Fig. 52.

Fig. 54 is a detail perspective view showing the package as completed by Fig. 52 40 within the cup illustrated by Fig. 53 and a sealing band over the package within the cup.

Fig. 55 is a top plan view of the bander attachment or organization together with a 45 portion of the mechanism of the main machine illustrated in dotted lines.

Fig. 56 is a side elevation showing portions in cross-section of the banding attachment or organization, parts of coöperating 50 mechanism being illustrated in dotted lines.

Fig. 57 is a side elevation with parts shown in cross-section and dotted lines looking toward the side of the machine opposite that illustrated by Fig. 56.

55 Fig. 58 is a transverse vertical section taken in the plane of the line 58—58, Fig. 55, looking in the direction of the arrows.

Fig. 59 is a sectional plan view of the bander attachment particularly showing the 60 shuttle and the position of the packages as expelled therefrom after the band has been applied thereto and the mechanism for expelling the completed packages.

Fig. 60 is a transverse vertical section

through the shuttle of the bander attachment and particularly illustrating the association of the coacting members thereof.

Fig. 61 is a longitudinal vertical section through the shuttle of the bander attachment and the receiving chute or guide for 70 the completed packages and illustrating the mechanism directly coöperating with the shuttle to reciprocate the latter.

Fig. 62 is a section taken in the plane of the line 62—62, Fig. 59, and showing the 75 means for discharging the completed packages and the mechanism for operating said means.

Figs. 63 and 64 are top plan views partially in section and broken away and illustrating the lower members of the shuttles and the manner of inserting the packages therein and the positions the packages occupy during the different movements of the shuttle.

85 Fig. 65 is a detail perspective view of a package showing the band attached thereto.

Fig. 66 is a top plan view of a portion of the bander attachment similar to that illustrated by Fig. 59 and showing the band 90 feeder, moistener and cutter mechanism.

Fig. 67 is a section taken in the plane of the line 67—67 of Fig. 66.

Fig. 68 is a detail vertical section on an enlarged scale of the moistening and feeding mechanism for the band and the correlative mechanism coöperating therewith for operating at intervals the discharge means for the completed packages.

Fig. 69 is a horizontal section taken in 100 the plane of the line 69—69, Fig. 68, and showing the intermeshing gears for the band feeding and moistening mechanism and the controlling mechanism for the discharge means for the packages and especially illustrating a clutch which permits the discharge 105 means for the packages to run back without interfering with the operation of the remaining gears.

Fig. 70 is a top plan view of the receptacle for holding the moistening liquid for the bander and illustrating the moistening roller in horizontal section and the carrying means therefor in top plan view.

Fig. 71 is a transverse section taken in the 110 plane of the line 71—71, Fig. 70.

Fig. 72 is a horizontal section taken in the plane of the line 72—72, Fig. 67.

Fig. 73 illustrates detail views in section and in elevation, partially broken away, of 120 the feed controlling means for the band.

Fig. 74 is a horizontal section taken immediately below the bed of the bander attachment and particularly illustrating the operating mechanism for the parts of said 125 attachment.

Figs. 75 and 76 are detail views in sectional elevation in different positions show-

ing a portion of the mechanism illustrated by Fig. 74.

Figs. 77 and 78 are respectively a plan view and cross-section of a portion of the 5 discharge chute with which the shuttle cooperates showing a heating means applied thereto.

The numeral 5 designates a feed table of suitable length and made up of any number 10 of components or parts that may be desired to give the same sufficient rigidity and held against displacement from a true horizontal plane by brace means 6 connected to the outer extremity thereof and also to a base 15 7 provided with legs 8, as clearly shown by Fig. 7. The table 5 is formed with a pair of grooves 9 extending longitudinally thereof in parallel relation fully from the outer end to a point near the inner end of 20 the table, endless chain belts 10 being freely movable in the grooves 9 and having hooks 11 projecting therefrom at intervals and forming portions of the links included in the chain belt organizations, as clearly shown 25 by Fig. 3. The hooks 11 are so disposed with relation to the chain belts 10 that angular heads 12 thereof will be directed inwardly relatively to the table 5, the heads 12 having considerable free edge extent, as 30 at 13, and forming distinct shoulders 14 with respect to the shanks 15 of the hooks. The hook shanks 15 are of such length as to dispose the angular heads 12 some distance above the upper surface of the table 5 for 35 a purpose which will be presently explained. The chain belts 10 are trained over inner and outer pairs of sprocket wheels 16 and 17 of similar dimensions, the outer pair of sprocket wheels 16 being mounted on a 40 shaft 18 and the inner pair of sprocket wheels 17 on a shaft 19. In its simplified form the table 5, as shown by Figs. 2, 5 and 6, is provided with a guide 20 having opposite upstanding side flanges 21 and grooves 45 22 opening into the grooves 9, but of less width than the latter, the horizontal portion of the guide projecting over the grooves 9 providing shields or partial top closures for the said grooves; and through the 50 grooves 22 of the guide the shanks 15 of the hooks project and have free longitudinal movement. As shown by Figs. 1, 3 and 4, a bridge attachment may be applied on the 55 table or secured in proper position to the table when its use is desired, said bridge attachment consisting of a horizontally disposed feed plate 23 projected inwardly from and below the top portion of a supporting arch or retention means 24 transversely disposed with relation to the table and having an angular space member 25 extending along one side thereof, the plate 23 being held between the side flanges 21 and the angular space member secured to one of said side 60 flanges, as clearly shown by Fig. 4. The

parts are so proportioned or distanced that the angular heads 12 of the hooks will be partially below the under side of the plate 23 when moving through the bridge, the latter plate having slots 26 corresponding to the slots 22 in the bottom of the guide 20, and by this means paper or other sheet material that may be fed to and moved along over the table by the hooks 11 may be caused to pass under the plate 23, and paper or other sheet material deposited on the plate 23 may be regularly fed inwardly by the edges 13 of the angular heads 12 of the hooks 11 and deposited over and in predetermined relation to the sheets or pieces of paper or other material moving or fed under the plate 23 at intervals. The angular space member 25 provides for feeding a sheet or a piece of paper or other material over the plate 23 having a less width than the paper or other material fed under the plate so that the lower pieces or sheets of paper may have a portion of one side edge of each exposed or unengaged by the sheets or pieces fed thereto from above. The bridge attachment as just explained will have the securing parts thereof so constructed that they may be removable applied to the table 5 at any position desired and removable completely when the use of said bridge attachment is undesirable, as in preparing certain classes of inclosures or wrappers. When the bridge attachment is used, the form of inclosure or wrapper is of that type in which the interliner is associated with the cup, and both the latter parts are folded together by subsequent operations of the machine, and after the charge of cigarettes of a predetermined number has been disposed on the combined interliner and cup. The table also has a pasting attachment mounted thereon so that it may be removed and shifted to different positions as may be desired, and as shown on an enlarged scale by Fig. 2 said attachment comprises a supporting frame 27 with a paste receptacle or trough 28 held thereby and with which distributing rollers 28 and 29 engage and contact with upper transferring rollers 30 which in turn contact with applying rollers 31, the rollers 28 and 29 and 30 and 31 all being of such construction as to practically perform the functions of conveying the adhesive material to the devices to which the latter material is adapted to be applied, or to so dispose the applying rollers 31 as to effectively distribute the adhesive material to the devices arranged to receive the same. The shaft or spindle 32 of the upper transferring rollers 30 is mounted in suitable adjustable bearing means, as at 33, for regulating the contact of the said rollers 30 with relation to the rollers 28, 29 and 31. The spindles or shafts 34 and 35 of the pasting attachment as well as the spindle or shaft 130

32 are projected from opposite sides of the frame 27, the spindle or shaft 34 extending outwardly from both sides of said frame and mounted in suitable bearings, and on 6 one end thereof is a sprocket wheel 36 and on the other end a pinion 37, the sprocket wheel being engaged by a chain belt 38 from a sprocket 39 on one end of the shaft 18. The spindles or shafts 32 and 35 of the 10 rollers 30 and 31 are projected from one side of the frame 27 and are provided with pinions 40 and 41 meshing with each other and the pinion 40 with the pinion 37 and whereby all of the rollers of the pasting 15 attachment for delivering the paste from the receptacle or trough 28 are given the proper direction of movement to evenly distribute the adhesive material on the peripheries thereof as well as to lift and convey 20 the adhesive material to the point of application. The frame 27 has an inward extension, as at 42, and in suitable longitudinally adjustable bearings 43 a transverse shaft 44 is mounted and extended outwardly 25 to one side of the table and provided with a sprocket wheel 45 over which the chain belt 38 is also trained, and, in addition, the shaft 44 adjacent to the sprocket wheel 45 has a gear or pinion 46 thereon and fixed 30 to rotate therewith. On the shaft 44 one or more segmental paste liners 47 are mounted and also oppositely projecting paste spotting arms 48 and 49, as clearly shown by Fig. 2. The spotting arms contact with the applying 35 roller 31 in line with the same so that the extremities thereof will both receive a quantity of adhesive material or paste, and the segmental liner is adapted to engage an inner similar roller 31, as shown by Fig. 40 8, the innermost roller 31 being somewhat wider than the outermost roller with which the spotting arms engage. The rollers 28 and 29 also differ in width so as to pick up relatively increased quantities of the adhesive 45 material, and the rollers 30 which respectively engage the rollers 28 and 29 correspond in width thereto and to the rollers 31 to which the transfer of the adhesive material is made. The shaft 44 rotates in 50 the direction shown by the arrow in Fig. 2 and the arms 48 and 49 apply spots of adhesive material or paste to different portions of the inclosure or wrapper passing thereunder, and the segmental liner or liners 47 55 operate to apply a line or lines of adhesive material or paste to the inclosure or wrapper between the points of application of the spots of adhesive material or paste by the arms 48 and 49 to the said inclosure or wrapper. Held on a suitable shaft 50 mounted in bearings depending below the table 5 is a combined pressure and guide disk 51 that is continuously rotated and operates to hold up the sheets or pieces of material or paper, 60 as the case may be, to receive the line of adhesive material or paste from the liner 47, the combined pressure and guide disk 51 rotating in and partially projecting through a slot 52 in the table 5. The shaft 50 is driven at a speed uniform with that of the 70 shaft 44 through the medium of the gear or pinion 46 which also meshes with a similar gear on said shaft 50. As hereinbefore stated, this pasting attachment may be shifted along the table in accordance with the 75 particular form of inclosure or wrapper that is to be prepared, and as shown by Fig. 1 this attachment is located near the outer end of the table with the liner feeding means at a distance inwardly therefrom so that the 80 one part of the inclosure or wrapper will receive adhesive material prior to the disposition thereon of the remaining part of the inclosure or wrapper from the bridge or plate 23. In the arrangement shown by Fig. 85 2, the pasting attachment is disposed in advance of the primary inclosure or wrapper, which is adapted to be folded about the bunch of cigarettes of any predetermined number and then folded and the package 90 shaped and subsequently inserted into a proper cup that may be previously formed or independently prepared and which will be more fully hereinafter explained. On the table 5 a supply and feeding means 95 for an outer wrapper or cup, plain foil, glacie, or plain paper with or without printing is arranged, said supply and feeding means, as shown by Fig. 1, being inwardly a distance from the pasting attachment, and as shown by Fig. 2 the latter attachment is inwardly a distance from the said supply and feeding means. The supply and feeding means comprises a frame 53 having upstanding side arms 54 with bearings 55 in their upper ends to removably receive the opposite extremities of a spindle 56 of a reel or roller 57 on which the foil or paper of any type is wound. The frame 53 is also so constructed as to provide a support 100 for the remaining devices of the supply and feeding means which will be presently explained and includes depending attaching members 58 to which a plate 59 is removably secured and engages the under side of the 105 table 5, the supply and feeding means as a whole being shiftable or movable on the said table as may be desired and in accordance with the character of the paper or material carried thereby, and as hereinbefore 110 indicated the pasting attachment may be either in advance or in rear of the said supply and feeding means. At the rear lower portion of the frame 53 a tension roller 60 is mounted, and in the forward portion of 115 the said frame is a shaft 61 on which a feed roller 62 is mounted and preferably has a peripheral covering 63 of rubber or other suitable material. The shaft 61 is mounted 120 in suitable bearings and projected at one end 125 130

beyond one side of the frame 53 and has a crank arm 64 fixed thereto, and attached to the end of the crank arm is a connecting rod 65 adjustably attached at its rear end in a 5 radial slot 66 of a crank disk 67 mounted on the end of the shaft 18 opposite that carrying the sprocket wheel 39. Through the medium of the crank disk 67 and the connecting rod 65 the feed roller 62 is rotated 10 in suitable timed relation through the movement of the chain belts or endless chains 10 and the hooks 11 thereof. A tension attachment is mounted to coöperate with the feed roller 62 and consists of arms 68 pivotally 15 connected to opposite side portions of the frame 53 above and slightly in rear of the roller 62 and continuous with forwardly projecting arms 69 having laterally extending weights 70 on the free ends thereof. At the 20 point of intersection of the arms 68 and 69, bearings 71 are provided and receive the spindle 72 of a roller 73 which is circumferentially grooved, as at 74, between the center and the ends thereof, as clearly shown 25 by Fig. 8, for a purpose which will be presently explained. At the points where the arms 68 are pivoted at the opposite side portions of the frame 53 above the feed roller 62, bearings 75 are mounted, and in these 30 bearings extend the opposite ends of a spindle 76 having an intermediate crank 77 carrying a tension roller 78. Attached to the spindle 76 within the opposite members of the crank 77 is the lower end of a tension 35 strap 79 which is thrown over the paper or material, as at 80, on the reel or roller 57, and to the free end of this strap a weight 81 is secured, said free end of the strap and weight depending loosely from the rear portion 40 of the roll of paper or material 80. The purpose of this strap 79 together with its weight 81 is to obviate slackness of the coils of paper or other material 80 on the roll or reel 57 so that the said paper or material 45 may be fed in taut condition with advantages in the control of a positive supply thereof. In advance of the feed roller 62 a fixed shearing die 82 is disposed at a downward and inward angle of inclination, and 50 secured to the top of this die is the lower end of a comb 83 having a plurality of fingers 84 that curve upwardly through the grooves 74 of the roller 73 and extend partially over the forward portion of the feed 55 roller 62 in close relation to the latter. An inclined reciprocating blade 85 is arranged to coact with the die 82, and to the upper portion of the rear side thereof a yielding coupling is applied and consists of an upper 60 fixed member 86 having a rearwardly extending projection 87, and below the said fixed member is a pivoted member 88 with a rear projection 89, and between the two projections 87 and 88 a suitable spring 90 is interposed to normally hold the member 88 in 65 spaced relation to the member 86. An inwardly projected angular extremity 91 of a reciprocating arm 92 is attached to the under side of the member 88 and its projection 89, said arm 92 being fulcrumed at one 70 side of the frame, as at 93. The arm 92 has a guard 94 secured to the under side thereof and disposed over one bearing 71 of the tension frame to limit the relative downward movement of the arm 92 and the parts carried thereby by engaging the bearing 71 below in the event of excessive operation of the arm 92 and its cutting or shearing blade 85. The arm 92 with its blade 85 is operated through the medium of a downwardly and 75 rearwardly inclined rod 95 having a lower yoke or bifurcated end 96 engaging a cam 97 fixed on a spindle or shaft 98, the latter shaft also having a suitable sprocket wheel 99 thereon engaged by a chain belt 100 extending rearwardly and trained over a sprocket wheel 101 on the shaft 18 inside the crank disk 67. The sprocket chain or belt 101 has its upper portion also operatively 80 associated with a direction sprocket 102 to 85 maintain the same in proper position relatively to the mechanism adjacent thereto in the arrangement shown by Figs. 1 and 7. The paper or other material 80 on the roll or reel 57 is drawn downwardly and rearwardly over the tension and guide roller 60 and then forwardly over the feed roller 62 under the tension roller 78, the tension frame being elevated slightly to clear the feed roller while the paper or other material 90 is being placed thereover. The paper is then continued over the feed roller 62 and forwardly and downwardly between the latter and the fingers or members 84 of the comb 83 and then over the top portion of the die 100 95 105 110 of the die 82 so that there may be no crumpling or disarrangement of the paper or other material in its exit or discharge from the supply and feeding means. As shown by Fig. 1, the supply and feeding means is arranged to deliver or discharge lengths or pieces of paper of a suitable character to the bridge attachment or onto the plate 20, whereas in Fig. 2 the supply and feeding means delivers the foil or paper directly to the table 5.

A coupon feed attachment may or may not be used with the machine, but when applied to the table 5 it will be preferably disposed in advance of the supply and feeding means just described, as shown for instance by Fig. 1, or said coupon feeding attachment may be in advance of the pasting attachment, as shown arranged in Fig. 1. This variation in application of the coupon feeding attachment is rendered possible in view of the fact that the attachment may be shifted as it is associated with the table 5 in such manner that it may be readily detached and applied to any part of the table where its function may be most effective and in accordance with the character of the inclosure or wrapper for the cigarettes to be prepared. The coupon feeding attachment is of a well known type and will therefore only be generally described, and it consists essentially of a frame 103 embodying a stack 104 in which the coupons are regularly arranged, as clearly shown by Fig. 1. The stack has a delivering slide 105 at the bottom operated through the medium of a rack 106 in engagement with a pinion 107 mounted on a shaft 108. At the opposite or outlet end of the coupon feeding attachment are superposed feed rollers 109 and 110 between which each coupon is discharged, and above the feed rollers is a shaft 111 carrying reciprocating arms 112 which extend back to the opposite side of the stack and regulate the discharge of the coupons in accordance with a well known construction. The lower roller 109 has a pinion 113 secured on the shaft 114 thereof, and as shown in the present instance said pinion 113 is operated through the medium of a gear or pinion 115 on the spindle or shaft 116 of an upper mounting roller comprised in a pair of said rollers 117 and 118. The spindle or shaft 119 of the lower roller 118 is also provided with a pinion or gear 120 which is held in mesh with the gear 115, and by this means motion is given not only to the mounting rollers 117 and 118, but also to the rollers 109 and 110 of the coupon attachment through the medium of the pinion 113 on the spindle or shaft 114 of the lower roller 109. The coupon feeding attachment as shown by Fig. 1 is arranged directly in rear of the mounting rollers 117 and 118 at the inner terminal of the bridge attachment, and

after the cup and interliner members are associated they pass over the feed table between the rollers 117 and 118 and at the same time a coupon is discharged between the rollers 109 and 110 and is also directed downwardly below the upper mounting roller 117 onto the combined cup and interliner and pressed into place simultaneously with the pressure exerted by these mounting rollers with relation to the cup and interliner. The upper mounting roller 117 is composed of a plurality of members of different widths produced by grooving the same so as to cause the said roller to clear the hooks 11 and the paste lines of adhesive material on the parts or members of the inclosure or wrapper moving between the two rollers 117 and 118. The coupon attachment may be used with the table shown by Fig. 2 without the bridge if found desirable to deliver a coupon to plain foil, glacine, plain or other paper, and operates similarly as when the bridge attachment is applied to the table. At a distance inwardly from the mounting rollers 117 and 118 and also inwardly beyond the inner sprocket wheels 17 engaged by the chain belts 10, a pair of regulating rollers 121 and 122 is mounted on the table, and the upper roller is carried by a pair of arms 123 fulcrumed at their outer ends, as at 124, so that the said upper roller may be elevated as desired to clear the table for any purpose that may be found necessary during the inward feed of the inclosure or wrapper members thereover. To facilitate the elevation of the upper roller, grips or projections 125 extend outwardly from the arms 123. The lower roller 122 will have a suitable rubber covering or be constructed of rubber or other analogous material so as to set up sufficient feeding adhesion between the two rollers, and the upper roller 121, as shown by Fig. 8, will be grooved at intervals to permit the pasted portions of the inclosures or wrappers to clear the said upper roller. On the end of the spindle or shaft 119 of the lower mounting roller 118 opposite that carrying the pinion or gear 120 is a sprocket wheel 126 over which is trained a chain belt 127, as clearly shown by Fig. 8, this belt running to and engaging a sprocket wheel 128 on the adjacent end of the shaft 19 carrying the sprocket wheels 17 for the feeding chain belts 10. The shaft 19 also has a second sprocket wheel 129 on the same end thereof or adjacent to the sprocket wheel 128, the sprocket wheel 129 having a chain belt 130 trained thereover and also extending downwardly and trained over a sprocket wheel 131 on a counter-shaft 132 having thereon a bevel pinion 133 meshing with a corresponding bevel pinion 134 on the main drive shaft 135 of the machine. The shaft 19 further has a gear 136 fixed thereon which meshes 130

with a transmission gear 137 in turn continually held in engagement with a pinion 138 on the adjacent end of the shaft or spindle 139 of the lower regulating roller 122, 5 and the opposite end of said shaft 139, as shown by Figs. 7 and 8, is provided with a sprocket wheel 140 over which is trained a chain belt 141 for transmitting motion to a lower delivering roller 142 having a smaller 10 roller 143 superposed thereover and mounted to operate effectively in disposing the inclosures or wrappers on a charging table 144 in a proper position to receive a charge of cigarettes and partially over a discharge 15 opening 145 beneath a plunger 146 vertically reciprocated at intervals through the medium of an arm 147 extending outwardly to the side of the machine and mounted on a rock-shaft 148 having an arm 149 at one terminal 20 provided with means, as at 150, to engage the groove in the inner face of a cam 151 mounted on the main drive shaft 135. The upper delivery roller 143 is also so mounted that it may be elevated to clear the 25 inclosure or wrapper thereunder for purposes of rearrangement or rectification in the feed or to remove an inclosure or wrapper that may not have been accurately assembled. Between the upper registering roller 30 121 and the upper delivery roller 143 an arched guide 152 extends over the table and each inclosure or wrapper passes from beneath the registering rollers under the guide to the delivery rollers. The function of the 35 registering rollers is to receive and regularly direct the inward movement of each inclosure or wrapper after it becomes disengaged from the hooks 11 which have been feeding the same inwardly, and it will therefore be seen that the said registering rollers 40 operate to regularly continue the progress of the inclosure or wrapper and which is accomplished by the positively driven roller 122, and conjointly operating with these 45 registering rollers are the delivery rollers which also engage the wrapper or inclosure and dispose the same on the discharge table 144 in such position that the plunger 146 will force the same with a charge of cigarettes 50 therein downwardly through the opening 145 and partially fold the wrapper or inclosure for a purpose which will be presently explained.

The table 5 intersects with and practically 55 forms a part of a bed 153 on which all of the mechanism aside from that carried by the table and as hereinbefore described is disposed, the operating mechanism for the several instrumentalities on the bed 153 being 60 disposed below said bed and supported by the base 7 and including the main drive shaft 135; and in referring to this operating mechanism it will be understood that the same will have suitable bearing devices 65 and supporting uprights to dispose

various parts thereof at proper elevations and also to the best advantage in operating the mechanisms or instrumentalities above. Hence in the description that will follow only a general reference will be made to 70 this mechanism as occasion may require to demonstrate the operating means of the several parts which will be hereinafter explained. One of the essential features of the bed 153 is the mechanism for feeding, 75 assembling and discharging bunches or charges of cigarettes that may be varied in number in accordance with the quantity desired in each package, and the machine is so organized that parts thereof may be replaced without in the least disorganizing the mechanism or displacing any of the main contributing elements. This cigarette feeding and distributing mechanism comprises a hopper 154, which is clearly shown 80 by Figs. 8, 9 and 11, and is provided at one extremity with a feed extension or table 155 by means of which the cigarettes in bulk are deposited in the hopper proper. The hopper has opposite inwardly converging side 85 walls 156 and 157 which continue their convergence in opposite directions until a throat 158 is produced by the closest approach of the hopper ends, the said ends from the throat diverging to provide an outlet 159 90 larger than the throat. The end walls 156 and 157 are secured at their lower inwardly positioned terminals to a distributing slide 160 having a downwardly converging opening 161 therethrough provided with transversely extending rods or wires 162 at different elevations. The slide 160 not only operates to distribute the cigarettes deposited therein from the hopper above, but also to reciprocate the hopper by means of mechanism 95 which will be hereinafter specified. The hopper 154 at points adjacent to the throat 158 and above the latter is provided with deflectors 163 and 164 on the opposing end walls and at different elevations, 100 said deflectors being adjustable to vary the position thereof relatively to the throat 158 through the medium of adjusting and guide screws 165 and 166 which are adapted to engage suitable slots, as indicated by dotted 105 lines in Fig 11. The lower extremities of the deflectors are bent inwardly at a downwardly curved angle respectively as at 167 and 168, the extremity 168 of the deflector 164 being at a distance above the angular 110 extremity 167 of the deflector 163. The purpose of these deflectors is to obviate a choke or jam of the cigarettes when they reach the throat 158, and it will be seen that the cigarettes will be directed over by the 115 lower angular extremity 168 of the deflector 164 toward and onto the lower angular extremity 167 of the deflector 163, and from the latter angular extremity the cigarettes will be thrown toward one end wall of the 120 125 130

hopper and gradually fall without obstruction through the throat in ample quantities for distribution in a manner which will be presently explained. The end wall, for instance that shown on the right in Fig. 11, of the hopper toward which the cigarettes are directed from the lower angular extremity 167 of the deflector 163 has an automatically operating placing element or agitator 10 thereon consisting of a flat spring 169 which is primarily shaped to conform to and normally engages the portion of the end wall and one end wall of the opening 161 of the slide 160, and in the lower portion of the 15 same end wall of the hopper an opening 170 is formed for the free movement therethrough of a horizontally disposed arm 171 which is held in fixed position and is projected through the opening 170 to engage 20 the lower portion of the placing means or agitator 169 and causes the latter to move into the hopper and opening 161, as shown by dotted lines in Fig. 11. This action of the placing means causes an over-rolling or 25 over-turning of the cigarettes above the rods or wires 162 to effect a better distribution of the cigarettes passing into and through the lower portion of the hopper and the opening 161 of the slide 160. From the foregoing 30 it will be seen that the cigarettes are not crushed or are not subjected to a misshaping pressure and in fact are handled very gently so that the contents thereof will not be lost or very little, if any, of the tobacco filling of the cigarettes will become 35 displaced, and the placing means 169 conjointly operates with the wires or rods 162 to cause the cigarettes to be distributed through the lower portion of the opening 40 161 more evenly and with better effect in the final assemblage than would be possible if the outlet from the hopper was without the devices just explained. The opposite end walls of the hopper adjacent to the slide 160 45 is provided with inclosed dust collecting chambers 172 which are enlarged toward their lower extremities and have downwardly and outwardly inclined bottoms 173. The hopper has communication with these 50 chambers 172 through the medium of openings or slots 174 formed in the adjacent end walls, and connected to the lowermost depending portions of the said chambers are outlet pipes 175. As shown by Fig. 10, the 55 slide 160 moves between side guides 176 formed as a part of a top ledge 177 of a cigarette assembling chamber 178 fixed on an elevated portion 179 of the bed 153. The ledge 177 at opposite ends of the chamber 60 has sufficient extent to form supports when cleared by opposite movements of the slide 160 to permit cigarettes to be deposited thereon, but the cigarettes so deposited are pushed into the chamber by the opposite 65 end walls of the opening 161, said end walls, as at 180, being downwardly and inwardly inclined and effectively operating as clearance means. The chamber 178 is divided by fixed vertical partitions 181 inclining regularly from the vertical center of said chamber toward the opposite ends thereof, and in the rear side of this chamber shields or baffles 182 and 183 of different dimensions are inserted and these baffles may be varied 70 as to the number of spaces between the partitions occupied thereby and in accordance with the number of cigarettes that may be predetermined to constitute each charge and as indicated by Figs. 24 to 43, both inclusive. The spaces between the partitions 181 are 75 fully open at the top of the chamber so that the cigarettes may be regularly distributed in all of the spaces up to the plane of the lowermost rod or wire 162 at least, and in the distribution of the cigarettes in the assemblng chamber between the partitions a 80 rolling action is imparted to the cigarettes, especially those that are held above and engage the filled spaces between the partitions, it being understood that as the cigarette 85 charges are successively expelled from the chamber 178 other cigarettes above gravitate and fill the spaces previously occupied by the charges expelled, and as the spaces between the partitions slightly flare toward 90 the ends of said partitions the cigarettes will be preserved in proper shape with very little, if any, waste of the tobacco filling thereof. Secured to the top portion or ledge 95 177 of the chamber 178 is a fixed yoke 184 that projects from one end of said ledge and to which the arm 171 is secured. Between the end member of the yoke 184 and the adjacent end of the slide 160 cushion springs 100 185 are interposed, and between these 105 springs and secured to the yoke is a stop rod 186, as clearly shown by Fig. 10, said rod being provided with adjusting nuts 187 and operating as a check means relatively to the slide 160 and whereby a vibration of 110 the said slide and the hopper carried thereby is produced which will cause a settling action of the cigarettes in the hopper and through the slide. The inner end of the rod 186 engages the center of the slide 160 and 115 said rod moves through the center of the end member of the yoke 184, the adjusting nuts 187 limiting the movement of the slide 160 toward the end member of the yoke or regulating the distance of movement in this direction of the slide in accordance with the position of the nuts 187 on the rod 186. The outer end of the rod 186 is also provided with adjusting nuts 188, and by means of this second set of nuts further adjustment relatively to the rod 186 and the end member of the yoke 184 may be made as 120 found necessary. When the slide 160 is forced over the ledge 177 toward the end member of the yoke 184 the springs 185 are 125 130

compressed, and upon the return stroke or release of the slide 160 the latter is instantly repelled or caused to move in the opposite direction for a short distance by the tendency of the springs 185 to resume their normal condition. It will also be observed that when the slide 160 is reciprocated toward the end member of the yoke 184, the arm 171 operates or is projected through the opening 170 and forces the place means or spring agitator 169 inwardly, as shown by dotted lines in Fig. 11, and the cigarettes are thereby pushed over toward the center of the opening 161 and between the rods or wires 162 so that the cigarettes may be more evenly and regularly distributed in the upper open spaces between the partitions 181 of the assembling chamber 178. A spring 189 is connected to the end portion of the hopper 154 opposite that with which the springs 185 coact, said spring 189 having its outer terminal fixed to a post 190 rising from the bed 153. The spring 189 also tends to move the hopper 154 back to the position shown by Fig. 11 or resists the movement of the hopper and the slide 160 over the ledge 177 of the assembling chamber 178 toward the end wall of the yoke 184. The means for positively reciprocating the slide 160 and the hopper 154 carried thereby consists of a connector 191 comprising a tubular body 192 with cylindrical heads 193 and 194 movably mounted in opposite ends thereof and having cross-pins 195 engaging slots 196 at diametrically opposite points in the tubular body 192, the said slots 196 being long enough to give the pins 195 ample play therein. The cylindrical heads 193 and 194 have inwardly projecting stems 197, one on each, and the said stems project into the opposite extremities of a coiled spring 198 movably mounted within the tubular body 192. The spring 198 tends to force the cylindrical heads 193 and 194 outwardly through the ends of the tubular body 192, and by this means a compensating action is set up in the connector so as to avoid jar or shock on the hopper 154 and the slide 160 carrying said hopper and also to effect a release relatively to the slide and hopper on the return or outward stroke so that the springs 185 may act and an effective vibration or settling movement given to the slide and hopper. The inner head 194 is pivotally connected to the center of the outer end of the slide 160, as at 199, and to the outer end of the outer head 193 an angle lever 200 is pivotally connected, the upper arm of said lever movably projecting upwardly through an opening 201 in the outer portion of the bed 153 and fulcrumed on a suitable bracket or hanger 202, as at 203, and having a lower arm carrying a suitable roller in engagement with a cam groove 204 of a cam 205 on a shaft 206 driven by a sprocket

chain 207 and suitable sprockets from the main drive shaft 135. At proper timed intervals the cam 205 through the medium of the groove 204 therein actuates the lever 200 to force the slide 160 and hopper 154 inwardly against the resistance of the springs 185 through the medium of the connector 191, and when the lever 200 first exerts an inward pushing action on the connector both heads 193 and 194 will move inwardly in reverse directions into the tubular body 192 against the resistance of the spring 198 and thus give a cushioned starting action relatively to the connector without imposing an abrupt shock or jar on the slide 160 and hopper 154. When the pins 195 strike the inner walls of the opposing slots 196 the slide 160 and hopper 154 will then be positively moved inwardly against the resistance of the springs 185 and of the spring 189, and as soon as the lever 200 has assumed a certain position through the shape of the cam groove 204 the slide 160 and hopper 154 are practically released and are forced outwardly in a reverse direction by the springs 185 and 189 tending to resume their normal conditions, and as a consequence an easy operation and vibration of the slide 160 and hopper 154 will ensue and the outward movement of the slide and hopper will be checked against too abrupt stoppage by the heads 193 and 194 again having an inward cushioning movement within the tube 192 against the resistance of the spring 198 and as a consequence a settling operation will be given to the cigarettes within the hopper, with advantages in gravitation of the same toward the opening 161 and eventually in the spaces between the partitions 181 of the assembling chamber 178.

An expeller or ejector 208 coöperates with the assembling chamber 178 and comprises a plurality of spaced fingers 209 which correspond to the number of spaces between the partitions 181 of the assembling chamber, the fingers 209 being of such length as to fully push the cigarettes outwardly from between the partitions or walls 181, a majority of the fingers being of such vertical extent as to engage the three lower rows of cigarettes between the said partitions. The fingers 209 will be modified as to their vertical extent, as shown by Figs. 24, 28, 32 and 36. In the form of the expeller or ejector shown by Fig. 24 there are three fingers on each side of the center of equal vertical extent, and at the center is a finger 210 having its upper edge flush with the adjacent upper edges of the remaining fingers and the lower portion thereof cut away or removed to form a recess or pocket 211 corresponding to the vertical distance of occupancy of one cigarette within the assembling chamber, and with this form of expeller or ejector the assembling chamber

178 will be organized as shown by Fig. 25 and having a lower baffle 212 at the center in addition to the upper baffles 182 hereinbefore described. By this means it will be seen that on opposite sides of the center of the assembling chamber there will be three rows of cigarettes in vertical position for discharge from each space between the partitions, and at the center there will be but two cigarettes, making the total number of cigarettes to be discharged amount to twenty. The recess or pocket 211 provides a clearance for the expeller or ejector 208 relatively to the baffle 212, and the central vertically reduced finger 210 will engage the two superposed cigarettes exposed above this baffle. As shown by Fig. 28, all of the fingers 209 of the expeller or ejector except that at the extreme right are of equal vertical extent and the outermost right-hand finger 213 has its lower edge flush with the lower edge of the adjacent fingers 209 but is vertically reduced relatively to the adjacent fingers to provide an upper recess or pocket 214, and the assembling chamber 178 with which this form of expeller or ejector is used is clearly shown by Figs. 11 and 29 and wherein the baffle 182 has a depending extension or baffle 183 over a portion of the outermost or right-hand cigarette receiving space, the remaining spaces between the partitions 181 being each exposed below the baffle 182 and containing three cigarettes in superposed relation, making a total of twenty cigarettes exposed in a different manner for ejection by the form of the expeller or ejector as shown by Fig. 28. The form of expeller or ejector 208 shown by Fig. 32 comprises three fingers 209 and a fourth finger 215 of comparatively small vertical extent and providing upper and lower recesses 216 and 217, the expeller or ejector shown by Fig. 32 being adapted to operate with the assembling chamber 178 reduced in dimensions for the discharge of ten cigarettes therefrom, the partitions 181 being arranged substantially the same as those shown by Figs. 11, 25 and 29, and also the upper baffle 182 with the extension or depending baffle 183 is similar to that shown in connection with the assembling chamber illustrated by Figs. 11 and 29. In addition to the baffles 182 and extension baffle 183 the chamber as shown by Fig. 33 also has a lower baffle 218 below the baffle extension 183 so as to provide for the ejection of a single cigarette only from the right-hand space of the assembling chamber. It will be seen that the expeller or ejector shown by Fig. 32 in coöperation with the assembling chamber as shown by Fig. 33 has ample clearance through the provision of the recesses or pockets 216 and 217 relatively to the baffles as arranged in Fig. 33. In the form of the expeller or ejector 208 shown by Fig. 36, two intermediate fingers 209 are of the same vertical extent, and the outer fingers 219 and 220 respectively have recesses or pockets 221 and 222 formed above and below the same by vertically reducing the said two outer fingers, the lower edge of the finger 219 being flush with the lower edges of the adjacent fingers 209, and the upper edge of the finger 220 being flush with the upper edges of the said fingers 209. The assembling chamber 178, as shown by Fig. 37, has the upper baffle 182 with the depending baffle extension 183, and instead of having the baffle 218 as arranged in Fig. 33 a baffle 223 is disposed at the lower portion of the left-hand space, and by this means two cigarettes in superposed relation are exposed in both the right-hand and left-hand spaces of the chamber with six cigarettes between them, and by this means ten cigarettes may be expelled or ejected by another arrangement and arrive at the same result. The expeller or ejector shown by Fig. 40 has all of the fingers 209 of the same vertical extent for the purpose of expelling fifteen cigarettes from the chamber 178, as shown by Fig. 41, and wherein all the baffles will be removed except the upper baffle 182 and thereby leave a series of three superposed cigarettes in each space between the partitions 181 fully exposed for discharge. It will be understood that these baffles may be disposed at different points other than those mentioned and will be so applied that they may be removed and changed as to location as may be found desirable or preferred, and likewise the expellers of different forms as explained may be substituted one for the other in accordance with the assembling chamber with which they are intended to operate. The assembling chamber 178 may also be replaced in the machine so that a chamber to accommodate the discharge of twenty, ten, twelve, or any other number of cigarettes may be effected. By this means one machine may be successfully operated to wrap or inclose various numbers of cigarettes in each package without modifying the essential features of the mechanism and with very little labor. It is intended that each machine be equipped with the additional accessories so that the interchange of parts may be accomplished. The purpose of expelling or ejecting the different charges of cigarettes as just explained irrespective of the number is to provide for an advantageous disposition of the cigarettes in each package and to compensate for the compression that is applied to each charge of cigarettes prior to its inclosure by providing spaces at different points or in so arranging the cigarettes that they will not be jammed or crushed to any such extent as to injure the cigarettes and also to provide for the formation of rounded corners

in each package without flattening or unusually distorting the cigarettes occupying the corner positions, as illustrated by Figs. 27 to 43, both inclusive, and wherein it will be observed that the corner cigarettes are symmetrically disposed and are shaped to give a rounded corner effect without undue compression or flattening of the same. The expeller or ejector 208 of whatever form may be used embodies a web 224 from which all the fingers 209 extend, the said web having a hinged coupling member 225 that is detachably secured to the forward extremity 226 of a slide 227 by means of a suitable pin 228 that may be readily removed. The hinged or pivoted connection of the expeller or ejector 208 makes it possible to temporarily dispense with the operation of the said expeller by throwing the same over rearwardly and permit the rectification of any irregularity or error relatively to the cigarettes in the assembling chamber 178 or for any other purpose without stopping the operation of the remaining mechanism. When the expeller or ejector 208 is thrown over rearwardly out of engaging position with relation to the assembling chamber 178 it may continue to reciprocate as long as desired without performing its discharging function relatively to said chamber. The slide 227 and its forward connecting extremity 226 move relatively in and to a guideway 230 secured on the bed 153 and in part forming a closure 231. The one edge of the slide 227 is formed with suitable rack teeth 232, as shown by Figs. 12, 14 and 18, and held in continual mesh therewith is a gear 233 secured on the upper end of a vertical shaft 234 projecting through the bed and mounted in suitable bearings 235 and 236 forming part of a bracket 237 secured to and depending from the under side of the bed. The lower end of the shaft 234 extends into a boxing or closure 238 at the lower end of the bracket 237 and has a pinion 239 fixed on the lower end thereof and held in engagement with a rack-bar 240 which extends horizontally through the boxing or inclosure 238 and is connected at its outer extremity to a fork 241 which slidably embraces or engages the shaft 206 adjacent to the side of the cam 205 opposite that engaged by the lever 200 heretofore described. The cam 205 in the side opposite that in which the groove 204 is formed is also provided with another contour of cam groove 242 which is engaged by a roller or projection carried as at 243 by the rack-bar 240 at the point of connection thereof with the slide yoke 241. The cam groove 242 is of such shape and extent that the rack-bar 240 will remain in a state of rest for a certain period and then be reciprocated inwardly and subsequently released for outward movement owing to the particular con-

tour of the cam groove 242, as shown by Fig. 18. Surrounding the shaft 234 is a coiled spring 244 which winds about the shaft when the rack-bar 240 moves inwardly and rotates the said shaft through the pinion 239 to effect a movement of the expeller or ejector 208 into the lower portion of the assembling chamber 178. After the rack-bar 240 has performed its maximum inward movement in accordance with the formation of the cam groove 242, the spring 244 on the shaft which has become wound on the latter immediately sets up a reverse movement or rotation of the shaft 234 to assist in returning the rack-bar 240 to its normal position and avoid undue wear and reduction of momentum and to also reverse the movement of the gear 233 to retract the expeller or ejector 208. The rack-bar 240 continues inwardly beyond the boxing or inclosure 238 and is offset at an angle, or two similar rack-bars may be used, and in either instance the single or double rack-bar has its inner extremity movable through a boxing or inclosure 245 carried at the lower end of a bracket 246 secured at its upper end to the under side of the bed and also provided with upper and lower bearings 247 and 248. In these bearings a vertical shaft 249 is rotatably mounted and has a coiled spring 250 engaging the same, and on the upper end of this shaft 249 is a gear 251 held under an inclosure 252 forming part of a guide 253. The lower end of the shaft 249 is provided with a pinion 254 which is held in continual mesh with the portion of the rack 240 extending through the boxing or inclosure 245. The gear 251 meshes with rack teeth 255 of a slide 256 connected to or forming part of a charge ejector 257 which operates simultaneously with the expeller or ejector 208 in relation to a traveling carrier 258 disposed to operate adjacent to the outlet side of the chamber 178, as clearly shown by Fig. 12, the said carrier being movable between opposite guides 259 and 260 extending transversely across the bed. The outlet side of the assembling chamber 178 is provided with converging directing walls to form a discharge throat 261, the rear edge of the traveling carrier 258 moving close to the front terminal of the said throat so that the charges of cigarettes from the assembling chamber 178 may be regularly forced into the said carrier by the fingers 209 of the expeller or ejector 208, the said expeller or ejector having such length of stroke as to fully force the charges of cigarettes from the assembling chamber 178 into the several members of the traveling carrier 258. This traveling carrier 258 comprises endless chain belts 262 movable over sprockets 263 mounted to rotate on shafts 264 supported by adjustable brackets 265 and 266 engaging the under side of the bed 153. The bed has a

depending lug or boss 267 between the brackets 265 and 266, and therein an adjusting screw 268 is mounted, as clearly shown by Fig. 13, said screw engaging the 5 inner terminal of the bracket 266 and operative to give the proper tension to the chain belts 262. The chain belts 262 have a plurality of pockets or traveling chambers 269 secured thereto at intervals and at such distances apart that when they arrive over the upper portion of the table they will closely abut or have endwise engagement and will be held against downward movement to effect a straight travel thereof by the portions 10 of the chain belts moving closely over the horizontal top surface of the bed. The chain belts and pockets or chambers 269 are movable upwardly through an opening 270 formed in the bed and downwardly 15 around the inner side edge of the bed. Each pocket or chamber 269 is open at its opposite ends and the front side 271 is vertically straight and the rear side has an inwardly extending angular offset 272 below which 20 the charges of cigarettes are held. The several components of the carrier 258 or the pockets or chambers 269 are regularly charged from the assembling chamber 178 and carry the charges therein outwardly or 25 away from the assembling chamber to a discharge chute 273 having vertical walls and fully open at the front and rear extremities and also having transversely alined side openings 274 and 275 for transverse movement therethrough of the several components or the pockets or chambers 269 of the carrier 258. At the top of the chute 273 is a cover 276 which is connected by a spring hinge at its inner side edge, as at 277, so 30 that the said cover may be raised from its outer side edge upwardly and inwardly to clear the chute and expose the component or pocket or chamber 269 of the carrier thereunder. The purpose of the carrier 258 is to allow examination and rearrangement 35 of the charges of cigarettes by an operator so that they may be in proper condition for disposal into an inclosure or wrapper. It will therefore be seen that through the medium of this carrier defective cigarettes may 40 be removed, or if any irregular discharge of the cigarettes from the assembling chamber 178 ensues they may be regularly disposed in the components of the carrier before and even after reaching the chute 273, and therefore the finally inclosed bunches 45 of cigarettes or the charges as delivered to the wrapping means will be less liable to imperfection and be more satisfactory in the final output. Moreover, the exposure of the 50 charges of cigarettes through the medium of the carrier 258 provides for the introduction therein of any device that may be desired by an operator standing adjacent to the machine. The charges of cigarettes suc- cessively conveyed into the chute 273 are discharged from the chambers or pockets 269 by the expeller or ejector 257 simultaneously with the charging of one of the pockets or chambers from the assembling chamber 178, the parts being so proportioned and arranged that as one chamber or pocket 269 is relieved of its charge of cigarettes, another chamber or pocket will be receiving a charge of cigarettes. The expeller or 55 ejector 257 is pivoted or hinged at its rear end, as at 278, to the forward extremity of the slide 256 in a manner similar to the expeller or ejector 208, and consequently the expeller or ejector 257 may be thrown over 60 rearwardly so as to cease to operate as a discharging means relatively to the components of the carrier 258 at any time that may be found necessary and without stopping the operating mechanism or interfering with 65 the continuous actuation of the slide 256. The cigarettes discharged from the components of the carrier 258 are delivered into a pressure chamber 279. As shown by Figs. 14 and 15, the bed at the points where the 70 chute 273 and the pressure chamber 279 are located is slightly elevated with respect to the remaining part of the bed and the adjacent portion of the table 5 intersecting the bed so as to permit the inclosure or wrapper 75 to be disposed under each charge of cigarettes on the discharge table or platform 144 partially over the opening 145 in a manner which will be presently explained. Furthermore, the expeller or ejector 257 is angularly reduced along one side edge, as at 80 280, to permit the one side edge portion thereof to move under the shouldered offset 272 of each pocket or chamber 269, said expeller or ejector being practically solid 85 or having a blunt vertically straight front edge 281, as clearly shown by Fig. 15, so as to squarely engage the adjacent ends of the charges of cigarettes in the successive chambers or pockets 269 and force the said 90 charges lengthwise into the pressure chamber 279. The object of this pressure chamber is to preliminarily subject each charge 95 of cigarettes to pressure exerted longitudinally of the cigarettes in order to arrange 100 the latter to the best advantage for discharge into and operation of molding means on the cigarettes after the latter have been placed in proper position in an inclosure or wrapper. As will be hereinafter explained, 105 each charge of cigarettes after disposal on the wrapper or inclosure therefor is subjected to a shaping or molding pressure, and during the latter pressure the wrapper or inclosure is regularly folded about and 110 parts thereof secured relatively to each charge. The pressure chamber 279 includes means for giving the necessary pressure to the charges of cigarettes, and said chamber 115 and the means coöperating therewith may 120 125 130

therefore be properly termed the preliminary pressure devices and comprise a vertical slide 282 mounted in a slide seat 283 at the inner portion of the base of a vertical flange 284 of the bed 153, as clearly shown by Figs. 10, 12 and 15. Over the upper edge of this vertical slide 282 a guard plate 285 is mounted and secured to the upper edge of the said flange 284, the guard plate 285 having an inner depending flange 286, as shown by Fig. 15, which embraces the upper portion of the slide 282. Adjusting screws 287 are also mounted in the flange 284 in longitudinal alinement and have inner extremities bearing against the outer side of the slide 282 to compensate for wear and obviate too loose movement of the latter. Secured to the inner side of the slide 282 is a longitudinal member 288 of a yoke 289, the latter having inwardly projecting angular arms 290 and 291 respectively at the outer and inner terminals thereof. Secured to the elevated portion of the bed 153 under the preliminary pressure devices and almost wholly within the forward portion of the yoke 289 is a plate 292 having an upwardly projecting guide eye 293, and in this eye a plunger rod 294 is mounted to reciprocate, said plunger rod also extending through the outer angular arm 290 of the yoke 289 and provided with a platen or pressure head 295 of suitable dimensions. The plunger rod 294 also has an exteriorly screw-threaded motion controlling sleeve 296 mounted thereon and provided with an outer stop head 297, said motion controlling sleeve being adjustably fitted in the inner angular arm 291 of the yoke 289 and normally having the rear end thereof projecting inwardly beyond the inner side edge of said arm 291. The plunger rod 294 has free reciprocating movement through the motion controlling sleeve 296 and the latter is held in its adjusted position by a set screw 298 engaging the arm 291 and impinging against the said controlling sleeve. The inner end of the plunger rod 294 has a coupling head 299 fixed thereto, and pivotally attached to said coupling head is a pitman or connecting rod 300 which extends inwardly toward the rear edge of the bed and is movably connected to the upper arm of a lever 301 projecting through an opening 302 in the bed 153 and fulcrumed on a bracket hanger 303 depending from the under side of the bed. The lower arm of the lever 301 carries a roller or other suitable device 304 which engages a cam groove 305 of a cam 306 also mounted on the shaft 206, and in view of this operating mechanism the plunger rod 294 is regularly reciprocated in timed relation to the discharge of the cigarettes into the pressure chamber 279 or into engaging position relatively to the preliminary pressure devices so that the several steps of assembling and preliminary preparation of the cigarettes may be carried on in regular sequence. The pressure chamber proper, as at 279, is defined by a substantially U-shaped wall 307 which is fully open toward the outlet of the discharge chute 273 and has the platen or pressure head 295 projected thereinto. The plunger rod 294 is surrounded by a spring 308 abutting at its opposite extremities against the eye 293 and the head 297 of the sleeve 296, the said spring acting as a cushion relatively to the plunger rod 294 and the platen or pressure head 295 thereof and also to return the removable parts of the preliminary pressure devices to normal position, as shown by Fig. 12, when the connecting rod 300 has completed its pressure stroke. In the operation of the plunger rod 294 the lever 301 actuated by the suitably shaped cam groove 305 of the cam 306 causes the connecting rod 300 to move toward the left, see Fig. 17, and therewith the pressure head 295 moves into the pressure chamber 279 a distance equal to that between the inner end of the sleeve 296 and the outer end of the coupling head 299, said movement of the plunger rod 294 and its pressure head 295 being against the resistance of the spring 308, and by this means a gradual primary pressure is exerted on the charge of cigarettes in the pressure chamber 279. This primary pressure operates to properly dispose the cigarettes previous to the more forceful pressure that will immediately be exerted thereon or when the inner end of the coupling head 299 strikes the adjacent projecting end of the sleeve 296, and when this latter engagement ensues the yoke 289, together with the chamber 279 as defined by the U-shaped wall 307, bodily moves and the charge of cigarettes is carried over into a delivery chamber 309 immediately under the plunger 146 and over the discharge or delivery opening 145 in the table or platform 144. The elevated portion of the bed 153 adjacent to the discharge or delivery opening 145 is under-cut, as at 310, to provide for the proper disposal of the wrapper or inclosure on the table or platform 144 over the opening 145, the charge of cigarettes being held in the delivery chamber or the directing means 309 therefor relatively to the opening 145 immediately above the portion of the wrapper or inclosure on which the charge of cigarettes should be placed. As soon as the charge of cigarettes has been moved outwardly into the chamber 309 the plunger 146 immediately acts and forces the cigarettes downwardly through the wall 307, which at this time is open both at top and bottom, onto the wrapper or inclosure and then into one of the pockets 311 of a mold wheel 312 which will be herein-after more fully explained. As soon as this

discharge of the cigarettes is effected, the wall 307 together with the yoke 289 and the plunger rod 294 and its pressure head 295 will immediately move inwardly, such inward movement being permitted in view of the position of the roller 304 at the lower end of the lever 301 relatively to the cam groove 305 of the cam 306 and the parts of the preliminary pressure devices are restored to normal position, as shown by Fig. 12, and ready to operate on a succeeding charge of cigarettes delivered into the pressure chamber 279. The pressure chamber 279 is normally closed by a top cover 313 which is hinged at a point adjacent to the outlet of the chute 273 so that it can be raised and thrown upwardly and inwardly in a longitudinal direction, the said cover 313 being so hinged that it will not fall below a normal horizontal plane, but may be raised at any time desired to inspect the charge of cigarettes held within the wall 307, which with the portion of the bed over which said wall has movement constitutes the pressure chamber 279. The cover 313, as shown by Fig. 15, is held in its horizontal position by an angle flange 314 secured to the free edge thereof and adapted to bear on the guard or guide plate 285. The delivery chamber 309, as clearly shown by Fig. 16, is practically fully open at the top and bottom and is provided at opposite sides with spring-controlled retaining members 315 having upper and lower flanges 316 extending inwardly toward each other and defining a space having normal proportions corresponding to the charge of cigarettes disposed therein in the manner just explained. These retaining members 315 have spring hinge connections, as at 317, to a flanged portion 318 of the adjacent bed or frame, the spring hinges of these members 315 being strong enough to hold the said members in normal position, as shown by Fig. 16, and to retain the charge of cigarettes at the opposite ends in proper position until the plunger descends and forces the cigarettes downwardly between the said members 315 and from between the outer member of the wall 307 and the pressure head 295, the retaining members 315 spreading gradually and without too much resistance as the pressure of the plunger 146 is exerted on the charge of cigarettes disposed therebetween. On the rear portion of the table or platform 144 is an upwardly projecting stop flange 319 with which one edge of the inclosure or wrapper has contact, the said flange 319 being so positioned relatively to the opening 145 as to cause the inward closure or wrapper to be properly positioned over the said opening and under the plunger 146 and whereby the charges of cigarettes will be placed on the wrappers with the best advantage in the subsequent folding operation of the wrappers about the cigarettes.

The mold wheel 312 comprises a disk member or body 320, the pockets 311 being formed at the periphery of said disk and of sufficient width and length to accommodate charges of cigarettes embodying different numbers in each charge in accordance with the package to be prepared. In each pocket is a supplemental bottom 321 which serves as a plunger, and connected to this bottom is an inwardly projecting stem or rod 322 having its inner end mounted in a guide ring or annular guide member 323. All of the stems or rods 322 are radially disposed and are movable outwardly and inwardly, the said stems or rods being free to move inwardly when relieved of impelling force in an outward direction and positively moved outwardly at intervals by mechanism which will be presently explained. Each stem or rod 322 also has an actuating pin 324 projecting therefrom at right angles, said pins being engaged in the first instance by a pressure head 325 on the free end of a rod 326 fixed to the longer arm 327 of a bell-crank lever 328. The bell-crank lever 328 is fulcrumed on the frame, as at 329, and has a rocking movement imparted thereto through the medium of a connecting rod 330 attached to the lower end of the shorter arm 331 thereof, the connecting rod 330 carrying a roller or analogous device 332 engaging a suitable groove in a cam 333 mounted on the drive shaft 135. The rod 330 has a yoked end 334, as shown by Fig. 9, to loosely engage the shaft 135 so that the said rod 330 is maintained in positive operating position relatively to the cam 333. The mold wheel 312 is mounted on a shaft 335 held in suitable bearings on uprights forming part of the frame so that the mold wheel will be held closely under the opening 145 to effect a close registration of the successive pockets 311 with the said opening 145. The mold wheel is given a step by step rotation through the medium of a Geneva plate or disk 336 also mounted on the shaft 335, the said Geneva plate or disk having radial slots or sockets 337 opening through the periphery thereof. There will be as many of these radial slots 337 as there are pockets or seats 311 in the mold wheel, and both the mold wheel and Geneva plate or disk are fixed on the shaft 335 and said shaft is rotated thereby or directly through the medium of the actuation of the said Geneva plate. The mechanism for actuating the Geneva plate consists of a suitably shaped cam 338 mounted on the shaft 135 adjacent to said Geneva plate and having a roller 339 peripherally engaging the same, said roller being carried on the end of a lever 340 fulcrumed adjacent to the cam, and also connected to the said lever and roller is an arm 341 terminally carrying a roller 342, the arm having a spring 343 connected thereto and to a portion of the 130

base 7 below and operating to maintain a constant yielding contact of the roller 330 with the periphery of the cam 338. The lever 340 with the arm 341 and roller 342 5 operates to lock the Geneva plate or disk 336 against movement at regular intervals or when the pockets or seats 311 of the mold wheel 312 register with the opening 145 through the table or platform 144, the said 10 lever 340, arm 341 and roller 342 being projected inwardly by the action of the cam 338 to cause the roller 342 to engage each successive slot 337, the spring 343 being distended when the roller 342 is projected into 15 each slot 337, and therefore the upward movement of the lever 340 and its arm 341 is against the resistance of the spring 343 and the latter tends to restore the lever 340 and arm 341 to normal position by exerting a 20 downward pull on the said parts, and when the lower portion of the cam 338 is reached or engaged by the roller 339 the roller 342 will be disengaged from the Geneva plate. Mechanism is provided for regularly rotat- 25 ing the Geneva plate 336 and shaft 335, and in turn the mold wheel 312 is similarly rotated, the extent of rotation of the Geneva plate or disk and mold wheel being such as to regularly dispose a pocket or seat 311 30 under and in registration with the opening 145 of the table 144. The rotation of the Geneva plate or disk 336, shaft 335 and mold wheel 312 is accomplished through the medium of a disk 344 mounted on a shaft 345 35 carrying a roller 346 adjacent to the periphery thereof. The roller 346 enters one of the slots 337 adjacent thereto or in the line of movement thereof just at the instant that the roller 342 is clearing another slot 40 337 in advance, and as the disk 344 rotates, the said roller 346 thereon bears against the opposing walls of the slot engaged thereby and causes the Geneva plate or disk, shaft 335 and mold wheel 312 to rotate one step, 45 and as the roller 346 is clearing or moving out of the slot 337 with which it has been in engagement the lever 340, arm 341 and roller 342 again come into play by the operation of the cam 338 in contact with the roller 50 339, and the roller 342 is caused to enter the slot 337 which will be then opposite or adjacent thereto and the Geneva plate or disk 336, shaft 335 and mold wheel 312 will be held against movement and at such time an 55 inclosure or wrapper with a charge of cigarettes will be forced into the pocket or seat 311 below and in registration with the opening 145. The shaft 345 is a stub shaft and is mounted in suitable bearing means, as at 60 347, see Fig. 8, and on the outer end thereof is a pinion 348 which meshes with a gear 349 carried by the drive shaft 135, the gear 349 and pinion 348 being so proportioned as to give the disk 344 with its roller 346 a 65 properly timed rotation to effect the actua-

tion of the Geneva plate or disk 336 and its coordinate parts in the manner hereinbefore explained. On the shaft 335 carrying the mold wheel 312 and the Geneva plate or disk 336 is a sprocket wheel 350 engaged by a 70 chain belt 351 which is also trained over a sprocket wheel 352 on a shaft 353 for controlling the feed of a cup carrier or conveyer 354 which will be presently explained. The upper portion of the chain belt 351 is 75 also engaged by a guide or direction roller 355 suitably mounted on an adjacent portion of the frame, as shown by Fig. 8, and whereby the chain belt 351 is given ample depression to clear the parts under which it moves. 80 A sprocket wheel 356 is also mounted on the shaft 335 and thereover a sprocket chain 357 is trained and also over a sprocket wheel 358 on the shaft 264 nearest to the shaft 335 and whereby the two shafts 264 and their 85 sprocket wheels 263 are regularly rotated to move the carriers 269 which receive the charges of cigarettes from the assembling chamber 78. It will therefore be seen that the mold wheel 312, the carriers 269, cup 90 conveyer 354 and plunger 146 all have a timed movement so that they will operate at regular intervals to carry on their respective functions and particularly to dispose successive charges of cigarettes in the pockets 95 or seats 311 of the mold wheel 312. The expellers 208 and 257 also have their operating mechanism connected up in timed relation to that of the mold wheel 312 and plunger 146 so that the charging of the 100 chamber 279 under the said plunger will be effected without intermission and each of the charges will be moved into discharging position relatively to the plunger 146 just at the time that each successive pocket or seat 311 105 accurately registers with the lower portion of the opening 145. As hereinbefore explained, the pockets or seats 311 are each provided with a supplemental movable bottom 321 and all of these 110 bottoms are moved outwardly through their stems or rods 322 at the time the charges of cigarettes are forced through the opening 145 by the plunger 146 into the said pockets or seats and the inclosures or wrappers on 115 which the charges of cigarettes are deposited are so disposed under the plunger 146 that a greater portion of each inclosure or wrapper will extend outwardly in the direction of the outer edge of the table or platform 144, and when each charge of cigarettes and its wrapper are forced downwardly into the pocket in position to receive them, one side of the wrapper extends outwardly or is free of the pocket to a greater extent than the opposing 120 side of the wrapper to complete the fold and inclosure of the charge of cigarettes in a manner which will be presently explained. The face of each supplemental bottom 321 is flat, and adjacent to the opposite side edges 125 130

of the supplemental bottom said face is given an upwardly and outwardly curved contour, as at 359, whereby curved corners are formed relatively to the portion of the 5 incomplete package forced into each pocket or seat 311. When the plunger 146 descends and forces the charge of cigarettes and wrapper thereunder into the pocket 311 below, the supplemental bottom 321 will be given a 10 limited outward movement through the operation of the bell-crank lever 328, the rod 326 and the pressure head 325, which then engages the actuating pin 324 of the said supplemental bottom, and the object of this 15 operation of the supplemental bottom is to slightly compress the charge of cigarettes with the wrapper disposed in the pocket or seat and also to hold the charge of cigarettes and incompletely folded wrapper in the 20 most advantageous position for partially completing the fold of the wrapper and subsequently discharging the wrapper and its charge of cigarettes into engagement with devices for completing the fold of the wrapper. 25 In other words, the supplemental bottom 321 offers a resistance to the depression of the charge of cigarettes and the wrapper partially folded therearound, and it will be seen that the supplemental bottom cannot 30 move inwardly at the time the pocket under the plunger 146 is charged, for the reason that the pin 324 on the stem or rod 322 of said supplemental bottom is in engagement with the pressure head 325 and at such time 35 the bell-crank lever 328 will be instantly held against receding movement by the engagement of the connecting rod or bar 330 with a portion of the cam 333 having such contour as to maintain the said bell-crank 40 lever in immovable position. After each pocket or seat 311 is charged, the mold wheel is shifted in the direction of the arrow, as shown for instance by Figs. 11, 17 and 19, and the longer projecting portion of the 45 wrapper is forced under a fixed segmental folding guard 360 and as a consequence the projecting portion of the wrapper is pressed firmly over on the remaining part of the wrapper and becomes secured by reason of 50 the adhesive substance applied to the wrapper at different points so that when each pocket arrives at a discharging point the opposite ends of the wrapper will be in position to form the end folds and complete the 55 inclosure of the charge of cigarettes. The segmental folding guard 360 is of such length that at least two of the pockets or seats are in operative position relative thereto at one time, and hence the wrappers 60 around the charges of cigarettes in the pockets disposed in operative relation to the said guard will be reliably folded, or the body folds of the several wrappers will have been completed before the incompletely folded 65 wrappers and their charges of cigarettes are discharged from the mold wheel 312. As shown by Fig. 16, the main bottom 361 of each pocket or seat 311 has an opening 362 through which the stem or rod 322 has movement, and to prevent too loose play of 70 the said rod or stem and also to maintain a certain amount of frictional engagement thereof with the wall of the opening 362 the main bottom 361 of the pocket is formed with a horizontal counter-bore 363 at one side 75 of the center which communicates with the opening 362, and therein is mounted a spring 364 bearing at its inner terminal directly on the portion of the stem or rod 322 exposed to said bore and engaged at its outer terminal by a screw 365 by means of which the tension of the spring may be regulated, it being understood that the bore will be screw-threaded to receive the said screw. On one of the uprights 366 of the frame a horizontally disposed channeled member or slide box 367 is secured, as clearly shown by Figs. 9, 17, 19 and 22, said slide box having an outer removable plate or covering 368, and from the bottom of the slide box depends a 80 lug or ear 369. In the slide box 367 a slide bar 370 is mounted to have free reciprocating movement, and one end of the said bar is formed with a head 371 carrying upwardly projecting arms 372 and 373 arranged in spaced relation to form a throat 374 therebetween which is open at both the upper and lower extremities. The arm 372 serves as a guard and is considerably longer than the arm 373 and has an upper curved 85 free extremity 375. The arm 373 has a convex bearing face 376 and serves as a pressure medium or element for engagement with the successive pins 324 on the stems or rods 322, the said pins 324 moving around and downwardly between the arms 372 and 373 and in accordance with the timed operation of the several mechanisms and of the mold wheel 312 each stepped rotation of this mold wheel brings one of the pins 324 between the arms 372 and 373 as shown and the stem or rod 322 carrying the pin 324 disposed between the arms 372 and 373 will be in horizontal 90 position and ready to be moved outwardly and correspondingly move the supplemental bottom 321 which also serves as a discharging head in forcing the incomplete packages from the mold wheel. The slide bar 370 and its head 371, together with the arms 372 and 373 therefor, constitutes the discharging 95 means co-operating with the mold wheel to readily relieve the latter of the incomplete packages of cigarettes which have been shaped to a certain extent by disposition in the pockets or seats 311, and to operate this 100 discharging means a bell-crank lever 377 is fulcrumed on the lug or ear 369 and has its longer arm 378 movably attached to a link 379 which in turn is attached to a depending projection 380 of the bar 370, the said lug or 105 110 115 120 125 130

projection 380 being located adjacent to the head 371. The shorter arm 381 of the bell-crank lever 377 has a lower angularly deflected extremity 382 of substantially elliptical shape and provided with an elongated slot 383 which is slidably engaged by a pin 384 carried at the upper extremity of a lever 385. The lever 385 has a roller 386 thereon engaging a suitable groove of a cam 387 also fixed on the shaft 135, the lever 385 being provided with a forked end, as at 388, to loosely engage the said shaft 135. The operating mechanism for the discharge means for the mold wheel as just described operates 10 in timed relation to the actuation of the said wheel, and the loose connection of the lever 385 with relation to the shorter arm 381 of the bell-crank lever 377 provides for a gradual discharge of the incomplete package 15 from each pocket coming into discharging alinement or coöperation with the discharging means, and moreover, the said connection of the lever 385 prevents sudden jar or a too strong impulse in the discharge of the 20 package in view of the operation of the shaping and pressure and folding devices which will now be explained. When each charge of cigarettes with its inclosure or wrapper is forced into a pocket of the mold 25 wheel, the supplemental bottom 321 is forced outwardly through the operation of the bell-crank lever 328, rod 326 and pressure head 325 to the position illustrated in dotted lines by Fig. 17, and when the plunger 146 descends the bell-crank lever 328 and the parts 30 just mentioned operating therewith to expel the supplemental bottom will be in condition to give way or will move downwardly owing to the shape of the cam groove of the cam 333 with which the roller 332 of the connecting rod 330 engages, and as a consequence the said supplemental bottom and plunger 146 will descend together until the 35 charge of cigarettes and its inclosure or wrapper have been disposed in the pocket 311 in position to receive the same and immediately the plunger 146 will ascend and the mold wheel have a stepped rotation imparted thereto and while moving around to 40 the point of discharge the supplemental bottoms of the pockets which are charged will remain inert for the reason that they have become disengaged from the pressure head 325 connected by the rod 326 with the bell-crank lever 328. By such operation the 45 charges of cigarettes will not become unduly crushed and the cigarettes with their inclosures or wrappers will be regularly moved downwardly without liability of spacing the 50 inclosure or wrapper and with the greater advantage of accurately placing the charges of cigarettes and their inclosures or wrappers within the several mold wheel pockets. It will also be understood that there will be 55 a slight pressure given to the charges of

cigarettes when they are forced downwardly into the pockets of the mold wheel, but this pressure will only serve to properly position the cigarettes with their inclosures or wrappers in the mold wheel pockets. 70

The shaping, pressure and active folding devices are in the main carried by an upright 388^a rising from the frame at a suitable distance from the uprights 366, and from this upright 388^a a projection 389 also 75 rises and supports the bearings at one end of the rock shaft 148 which controls the movement of the plunger 146, the said projection being provided with a web 390, as shown by Fig. 17, with an opening 391 in 80 the lower portion thereof continuing into a horizontal fixed bottom plate 392. From the under side of the fixed bottom plate 392 a horizontal fixed support 393 also projects inwardly, and intersecting the lower end of 85 the segmental folding guard 360 is a top plate or wall 394, the support 393 and wall 394 constituting a fixed pocket into which the charges of cigarettes with their incompletely folded inclosures or wrappers are 90 successively discharged by the supplemental bottoms or plungers 321 of the pockets 311 of the mold wheel. Between the support 393 and wall 394 an outer wall 395 is interposed and has a fixed position, and this 95 outer wall 395 is centrally bored, as at 396, see particularly Fig. 20, and coöperating with the said wall 395 is a movable head consisting of separable members 397 and 398, the member 397 having an elongated 100 sleeve 399 extending through the bore 396 and the member 398 having a stem or rod 400 secured thereto and slidable in the sleeve 399 and also extending rearwardly and loosely passing through an upright or arm 105 401 carried at the rear extremity of a slide 402. On the stem or rod 400 between the wall 395 and the upright or arm 401 a set collar 403 is mounted, and between said collar and the upright or arm 401 a spring 404 110 engages the rod or stem 400. The rod or stem 400 projects some distance in rear or outwardly from the upright or arm 401 and also has thereon a set collar or stop 405. The set collar or stop 405 operates to limit the 115 inward movement of the rod or stem 400 together with the head member 398 fixed to said rod or stem. The head member 398 has a lower concaved projected edge 406, and the head member 397 has a corresponding 120 upper concaved projected edge 407, these edges 406 and 407 of the two members corresponding to the curved or concaved side portions 359 of the supplemental bottoms, plungers or followers 321 mounted in the 125 pockets 311 of the mold wheel 312, and by means of these concavities the corner portions of each package are given a convex contour instead of being pressed angularly, and as a consequence the cigarettes are like- 130

wise preserved in their convex form, especially those located at the corners of each package. The member 397 has a recess 408 around the bore 396, the recess being of a 5 depth equal to the thickness of the member 398 so that the latter may be pressed back into the member 397 and form a flush joint between the two members. The rod or stem 400 at the point where it engages the member 10 398 is provided with a collar 409 so that the said rod or stem will be effective in forcing the member 398 inwardly; and to accommodate this collar the vertical wall of the recess 408 around the bore 396 has a seat 15 410 formed therein to receive the said collar 409, as clearly shown by Fig. 20. The outer wall 395 is also provided with outwardly projecting sockets 411, as clearly shown by Fig. 21, to receive cushion springs 20 412 which have their inner ends engaging recesses 413 formed in the adjacent side of the member 397 of the sectional head. The springs 412 permit the member 397 to be forced outwardly with a cushioning effect, 25 and the inner side of the wall 395 has a seat recess 414 therein to receive the member 397 when the latter is forced outwardly its maximum distance, and as hereinbefore explained the recess 408 in the member 397 receives the 30 member 398 so that all the parts of the sectional head in their receding movements are permitted to give way and in their maximum outward projection occupy a close position relatively to each other and form a 35 resisting or obstructing means, yet in the primary shaping and pressing operation the head composed of the separable members yields sufficiently to avoid sudden and too great pressure exertion on the packages of 40 cigarettes fed into the fixed pocket embodying the support 393, top plate or wall 394, and outer end wall 395, to avoid creasing or deforming the packages while the last long fold is being made during ejection of the 45 packages from the mold wheel into the pressure means. In this pocket the packages of cigarettes are completed as to their shape and are given the final pressure, and the inclosure or wrapper is then completely folded 50 or the ends are closed, the fold of the inclosure or wrapper around the body of the package of cigarettes being fully completed when the several packages are discharged into the fixed shaping and pressing pocket 55 just described. The incomplete packages of cigarettes successively received from the mold wheel pockets 311 are gradually moved into the fixed shaping and pressing pocket and the overlapping fold of the inclosure or 60 wrapper produced by engagement of the projecting portions of the latter with the folding guard 360 projects beyond the width of the adjacent side of each package and is held between the portions 415 of the periphery of the mold wheel and the said guard 65

until each pocket 311 arrives opposite and registers with the fixed shaping and pressing pocket and until the supplemental bottom 321 of each pocket 311 operates as a discharging means, and at such time the 70 portion of the inclosure or wrapper which extends across the one side fold around the charge of cigarettes is caused to lap over and be pressed against the said one side fold by being brought into engagement with 75 the top plate or wall 394 and becomes secured by the final folding operation which takes place at the opposite ends of each package. When each package is delivered into the fixed shaping and pressing pocket 80 the ends of the inclosure or wrapper of each package project outwardly beyond opposite sides of said fixed pocket in position for a practical formation of the end folds and complete inclosure of the charge of cigarettes, said end folds being formed in a manner which will be presently explained. The slide 402 carrying the upright or arm 401 at its rear extremity has a pair of depending spaced lugs 416, and between these lugs 85 90 the upper end of one arm 417 of a bell-crank lever 418 loosely projects, said upper end of the arm 417 of this lever being provided with an antifrictional roller 419 as clearly shown by Fig. 17. The bell-crank lever 418 95 is fulcrumed as at 420 on the upright 388^a, and the lower arm 421 of this lever projects inwardly a suitable distance and is provided with a roller 422 at its free end which is held in continual engagement with the edge 100 of a cam 423, as shown by Figs. 17 and 19, mounted on the shaft 135, said cam having oppositely disposed cam projections 424 and 425, the cam projection 425 being wider than the projection 424. The roller 422 of the 105 arm 421 of the bell-crank lever 418 is held up in proper engaging position relatively to the edge of the cam 423 by a spring 426 secured to the arm 421 and also to a part of the frame, as at 427. The portions of the 110 cam 423 between the projections 424 and 425 are concentric with relation to the shaft 135 so that when the roller 422 engages these intermediate portions of the cam 423 the slide 402 will remain inactive, but as soon as the projection 424 engages the roller 422 115 and continues such engagement, the arm 421 of the bell-crank lever is forced downwardly and outwardly and as a consequence the arm 417 is moved inwardly and the slide 402 is 120 correspondingly shifted. As the slide 402 moves inwardly toward the mold wheel the upright or arm 401 likewise moves in the same direction over the rod or stem 400 and slightly compresses the spring 404, and this 125 compression of the spring acting against the collar 403 causes the member 398 to be moved in advance of the member 397 and the latter member being released in this manner is separated through the action of the springs 130

412 from the inner side of the wall 395, the compression of the spring 404 and the separation of the members 397 and 398 in the manner shown by Fig. 20 being effected as 5 the pressure head comprising the said separable members reaches the inner inlet to the fixed pocket for shaping and pressing the packages, and the parts 397 and 398 of the head arrive at the inner inlet of the said 10 fixed pocket just at the time that one of the pockets 311 carrying an incompletely folded charge of cigarettes accurately registers with the fixed pocket, and immediately the discharging mechanism coöperating with 15 the stem 322 and the supplemental bottom or follower 321 begins to operate as hereinbefore explained and the said supplemental bottom or follower forces the incompletely inclosed package from the pocket 311 of the 20 mold wheel against the member 398 and said member moves outwardly in the same direction as the supplemental bottom or follower 321 is moving until the member 398 is engaged in the recess 408 and then both members 397 and 398 move outwardly against the resistance of the cushion springs 412 engaging the member 397 and also against the resilient action of the spring 404 which is then compressed in an outward direction by 25 the collar 403, and at this time the roller 422 will have become disengaged from the projection 424 and the concentric portion of the cam opposite that in engagement with the said roller, as shown by Fig. 19, will 30 then have operative contact with the same roller. When the member 398 is moved inwardly by the operation just explained and as clearly shown by Fig. 20, and the member 397 is thereby released so that the springs 35 412 operate to automatically push the said member 397 inwardly, the sleeve 399 shifts in the bore 396 and the movement of the said member 397 in an inward direction is limited by a stop collar 428 on the sleeve 40 45 striking against the central projecting portion of the bearing 429 at the center of the outer portion of the wall 395 around the bore 396, the outer side of the wall 395 being hollowed out as shown to condense the organization of parts coöperating with this 50 wall and particularly to obtain the operation of the sleeve 399 as described without having a long rearward projection thereof at the outer limit of the wall 395 as would be 55 the case if said latter wall was solid instead of hollowed or cored out as shown. Secured to the web 390 and the adjacent portion of the upright 389 is a bracket 430 having a lower opening 431 to clear the portions of 60 the rod or stem 400 and stop collar 405 located outwardly beyond the arm 401. In this bracket a shaft 432 is mounted to rotate in suitable bearings, and on the shaft 432 a ratchet wheel 433 and a pressure regulating disk 434 are fixed to move with the 65 shaft. The pressure regulating disk 434 has its periphery regularly provided with clearance seats or notches 435 and stop projections 436 with straight bearings edges 437, the inner wall of each notch 435 continuing through 70 an outwardly inclined edge 438 to the straight edge 437 of the projection 436. This notched and stop projection construction just explained continues regularly around the disk 434 and the edge of this disk stands opposite 75 the outer free end of the rod or stem 400, and as the ratchet wheel 433 is rotated in the direction of the arrow shown by Fig. 19 the disk 434 is similarly rotated, the rotation of both the ratchet wheel and 80 disk being of a step by step character and the parts so proportioned that each stepped rotation will alternately bring one of the stop projections 436 into an engagement position relatively to the outer free end of the 85 rod or stem 400 and one of the notches 435 in like position relatively to the outer end of said rod or stem. When the successive projections 436 are in engagement position 90 relatively to the outer end of the rod or stem 400, the outward movement of the stem will be limited, and the object of this particular mechanism is to control the pressure exerted on each package discharged from the mold wheel into the fixed pocket for receiving the same so that there will be a uniformity in pressure on each package and all of the packages will be of similar dimensions when discharged from the said fixed pocket. The particular mechanism as just 95 explained may therefore be properly termed "pressure controlling mechanism" having the function of maintaining uniformity of pressure on all of the packages discharged or delivered into the fixed receiving pocket where the final shaping and pressing and completing of the inclosures or wrappers are accomplished relatively to the successive packages. The pressure controlling mechanism is operated through the 100 medium of a connecting rod or bar 439 attached to the upper end of the arm 417 of the bell-crank lever 418 and also movably connected to the lower end of a swinging arm 440, said arm being attached 105 at its upper extremity to the shaft 432. The swinging arm 440 carries a pawl 441 which is held in continual engagement with the teeth of the ratchet wheel 433 by a spring 442 connected to the said pawl and 110 the lower portion of the arm 440. It is obvious that the pawl 441 will cause the ratchet wheel 433 to rotate in the direction of the arrow when the connecting rod or bar 439 is drawn inwardly with the arm 417 of the 115 bell-crank lever 418, and on the outward return movement of the connecting rod or bar 439 the said pawl will engage another tooth of the ratchet wheel 433 and thereby bring successive notches 435 and projections 437 120 125 130

into engagement position relatively to the outer free end of the rod 400. When the rod 400 and slide 402 move outwardly and the members 397 and 398 are caused to advance in the fixed receiving pocket, the pressure controlling mechanism adjacent to the outer end of the rod 400 is simultaneously operated to bring one of the projections into engagement position with relation to the outer end of the rod 400, and pressure exerted on each package disposed or discharged into the fixed pocket will be rendered uniform by reason of the fact that the outward movement of the rod 400 will be limited and when the members 397 and 398 recede or move outwardly with the follower 321 a check at the limit of the outward movement of said parts will be set up by the projection 436 then in registration with the outer end of the rod or stem 400. When the roller 422 is passed by the projection 424 of the cam 423 and the said roller engages the concentric portion of the said cam opposite that shown by Fig. 19 as hereinbefore explained, the outward movement of the rod or stem 400 and the head comprising the separable members 397 and 398 is permitted to take place, the said outward movement being effected to fully dispose each incompletely folded package within the fixed pocket and the supplemental bottom or follower 321 of the mold wheel in registration with the fixed pocket will move with the package into said latter pocket, as shown by Fig. 17, and at the same time the rod or stem 400 will be prevented from having a full backward movement owing to the fact that a projection 435 of the pressure controlling mechanism is then in engagement relation to the outer free end of the said rod, and, moreover, the outward movement of the parts just explained will have a cushioning effect on each package delivered into the fixed pocket by reason of the springs associated with the several parts as hereinbefore explained. The teeth of the ratchet wheel 433 are cut in such manner and divided as to cause the compression regulating disk with its notches 435 and its projections 436 to move in regular position relatively to the rear or outer end of the rod 400, said ratchet wheel being operated through the medium of the arm 440, rod or bar 439 and bell-crank lever 418 in engagement with the cam 423, the first low point of the said cam causing the bell-crank lever to rock through the action of the spring 420 so that the arm 417 will move to the rear and correspondingly move the rod or bar 439 and the arm 440, thereby carrying the pawl 441 therewith over the teeth of the ratchet wheel 433 or the distance of one ratchet tooth, and in this position a notch 435 will be opposite to and engaged by the rear end of the rod 400, the said rod 400 under this condition being prevented from having bodily movement the least distance farther to the rear, and the movable head of the compression pocket and comprising the separable members 397 and 398 will be in the position shown by Fig. 19, or the head member 398 will be pushed outwardly against the head member 397 by the package delivered thereinto from the mold wheel, and when the head member 398 reaches this outward limit and the springs 414 are fully compressed the head members 397 and 398 as well as the rod 400 will be fixed as a resistance means during the delivery of the package. As soon as the high part or projection 424 of the cam 423 engages the end of the arm 421 of the bell-crank lever 418, said arm is forced downwardly and rearwardly and the upper arm 417 of the same bell crank lever is moved inwardly, thereby exerting a pull on the rod or bar 439 and the arm 440 to cause the pawl 441 to shift the ratchet wheel 433 the distance of one tooth, and such movement of the ratchet wheel will in turn rotate the disk 434 a corresponding distance to bring the succeeding projection 437 into engagement with the rear end of the rod 400, thereby forcing said latter rod and the head members 397 and 398 inwardly to exert a compression on the package in engagement with said head members and subsequently the folds at the ends of the package are completed. When the package has been fully delivered or discharged into the fixed pocket the preliminary end folds are formed by upper and lower vertically aligned folding blades 443 arranged in pairs at opposite ends of the fixed pocket and movable closely over said ends, the upper blades 443 being carried at opposite sides of a horizontal arm 444 of a vertically reciprocating bar 445 and the lower blades 443 being carried by a horizontal arm 446 at the upper end of a vertically reciprocating bar 447. The bars 445 and 447 respectively move in suitable guides 448 and 449 at one side of the upright 388^a, as clearly shown by Fig. 18, and the lower portions of the inner edges of said bars 445 and 447 are provided with gear teeth 450, thus constituting the said bars, in part at least, as rack bars; and between the teeth 450 and held in continual engagement therewith is a pinion 451 which in turn is engaged by a toothed segment 452 fulcrumed at its lower end, as at 453, on the upright 388^a. The pinion 451 is of such dimensions that it may be easily engaged by the toothed segment 452, the latter having a swinging movement over the lower extremities of the guides 448 and 449 and the vertically reciprocating bars 445 and 447. This pinion 451 is suitably mounted between the reciprocating bars 445 and 447 on the upright 388^a, and the actuation thereof by the segment 452 effects an instant reciprocation of the 190

bars 445 and 447 in reverse directions, the bar 445 being drawn downwardly and the bar 447 being simultaneously elevated so that the pairs of blades 443 will simultaneously engage the opposite ends of the package held in the fixed pocket and form the first end folds relatively to the wrapper. The horizontal arms 444 and 446 are extended relatively to their respective bars 445 and 447 to properly position the blades 443 and cause the opposite pairs of blades to just pass the opposite sides of the fixed pocket. The blades 443 are removably held by the arms 444 and 446 and may be replaced by other similar devices when found necessary, and it is preferred that these blades have their free ends rounded and blunt so as to engage the upper and lower end portions of the wrapper without injuring the latter. On the toothed segment 452 a roller 454 is mounted and held in continual engagement with a cam 455 fixed on the shaft 135 by means of a spring 456 attached to the spindle of the roller 454 and to a portion of the base 7, as clearly shown by Fig. 18. The cam 455 is so shaped that at intervals the toothed segment 452 will be actuated to effect a rotation of the pinion 451 and a resultant actuation of the bars 445 and 447 in reverse directions to move the blades 443 into engagement with the upper and lower projecting portions of the wrapper around the bunch of cigarettes in the fixed pocket. It will be understood that the folding blades 443 and their bars 445 and 447, together with the operating mechanism therefor, will have a properly timed operation relatively to the remaining mechanisms and immediately subsequent to the recession of the folding blades 443 from the package ends the first side folds are then made through the medium of an oscillating arm or lever 457 fulcrumed on the lower portion of the upright 388^a, as at 458. The oscillating arm or lever 457 has a head 459 at its upper free end carrying a pair of folding blades 460 which are spaced and movable closely over opposite sides of the fixed pocket and the adjacent portion of the mold wheel, the head 459 having a yoke formation to permit the clearance of the adjacent portion of the mold wheel and the fixed pocket. The oscillating or swinging arm or lever 457 carries a roller 461 which engages a suitable cam groove in the cam 455, said cam groove being so shaped that the arm or lever 457 will be swung outwardly over the fixed pocket at regular intervals or just subsequent to the operation of the folding blades 443. The final fold at the outer end of the package is made by standing folding blades 462 secured to the front extremity of the slide 402, said blades 462 moving in close relation over the opposite sides of the fixed pocket and operating

simultaneously with the slide 402. From the foregoing it will be seen that in folding the opposite ends of the wrapper or enclosure the first folds are made at the upper and lower portions in reverse directions over the opposite ends of the charge of cigarettes and then at the side from the inner portion of the wrapper outwardly, and finally at the outer side inwardly over the remaining side folds previously formed, the upper and lower primary folds being inclosed by the side folds. This formation of the folds ensues relatively to all kinds of inclosures that may be used, whether the wrapper comprise an interliner or be of a single thickness of material, such as foil. As hereinbefore specified, the preliminary inward movement of the slide 402, rod or stem 400 and head comprising the separable members 397 and 298 is accomplished through the engagement with the roller 422 at the lower extremity of the bell-crank lever 418 of the projection 424 of the cam 423, and when the said roller 422 bears upon or engages either of the concentric portions of the said cam relatively to the shaft 135, the slide 402, rod or stem 400 and head connected with the said rod remain in a state of rest, and when the projection 425 of the cam 423 engages the roller 422 the slide 402, together with the rod or stem 400 and the separable or sectional head comprising the members 397 and 398, are given a positive inward movement to set up a shaping pressure relatively to the package held between the members 397 and 398 and the supplemental bottom or follower 321, and during this shaping pressure the folding operations above explained or the blades 443, 460 and 462 sequentially operate and after the projection 425 passes over the roller 422 the bell-crank lever 418 returns to normal position, as well as the slide 402, and the stem or rod 400 and the ratchet wheel 433 will have been operated to cause a notch 435 of the disk 434 to be in engagement position relatively to the outer free end of the rod or stem 400. The pairs of blades 443 held by the bars 445 and 447 are secured to rocking heads 443^a pivotally connected to the horizontal arms 444 and 446, as clearly shown by Fig. 9^a, the inner ends of said rocking heads being inclined in reverse directions, as at 443^b, and normally bearing against separating wedges 443^c, the upper wedge having its reduced extremity at the upper end thereof and the lower wedge having its reduced extremity at the lower end. These wedges 443^c are held in proper fixed positions by the top plate 444 and the support 398. The pairs of rocking heads 443^a have pins 443^d projecting therefrom, one from each head, and to each pair of pins the opposite ends of a retractile spring 443^e is secured. The normal position of the blades 443 is outwardly in divergent planes, the

blades being held in this position by the springs 443^e, and when the bars 445 and 447 are reciprocated to cause the blades 443 to perform their folding functions, the said 5 blades are gradually drawn together or inwardly by the wedges 448^e engaging the inner inclined ends of the heads 443^e against the resistance of the springs 443^e, the object of this movement of the blades being to 10 force the upper and lower portions of the projecting wrapper at the ends of the package downwardly and inwardly against the charge of cigarettes and provide for the practical formation of a lapped fold which 15 is completed by the blades 460 and 462 as hereinbefore explained. When the blades 443 recede from folding positions relatively to the wrapper the remaining side folds have been completed or the blades act to retain 20 the upper and lower portions of the wrapper in place until the end folds are completed, and then the blades resume their normal position or recede from the opposite ends of the package. The package having 25 been completely inclosed or the end folds properly formed and shaping pressure having been imparted to the package, the latter will then be ready for discharge from the fixed shaping and pressing pocket, and 30 if the package is to be inserted in a cup the cup carrier 354 will be supplied with cups to receive the completed packages which are expelled from the fixed pocket. The cup carrier shown is the same as that described 35 in my Patent No. 890,402, dated June 9, 1908, and embodies a conveyer belt 463 having throat links 464 from which project a series of spring blades 465 on which the cups 466 are frictionally held, as clearly shown 40 by Figs. 8 and 9^a. A feed table 467 projects outwardly from the bed 153 of the machine and is supported by a suitable bracket 468 having bearings at opposite ends for sprocket wheels 469 and 470, the bearing for 45 the sprocket wheel 469 being held at the outer terminal of an adjustable arm 471 which is movable through the medium of an adjusting screw 472. The endless belt 463 includes the sprocket wheels 469 and 470, 50 the sprocket wheel 470 being mounted on the shaft 353, and the latter is rotated at intervals through the operation of the chain belt 351 from the shaft 335 on which the mold wheel 312 and the Geneva plate or disk 336 are mounted, and consequently a step by step feed of the endless belt with the cup carrying means and the cups or the cup conveyer 55 is provided relatively to the movement of the mold wheel and the remaining mechanism and whereby a throat link and a cup will always be in registration with one side of the fixed pocket in which each package is shaped and compressed and the wrapper completely folded just at the interval that the discharge 60 of the completed package is necessary in order to clear the fixed pocket for a subsequent discharge thereinto of an incompletely inclosed and shaped package. The endless belt 463 is, of course, adjusted to compensate for slackness through the medium of the arm 70 471 and screw 472. An operator regularly applies the cups 466 on the blades 465 from the table 467 and the discharge of the completed packages from the fixed pocket embodying the means for shaping and pressing 75 the package as well as folding the ends of the wrapper is effected by mechanism which will now be described.

The means for discharging the completed packages from the fixed pocket into which 80 the incomplete packages are discharged from the mold wheel comprises a plunger 474, as clearly shown by Fig. 9^a, having a rod 475 connected to a slide 476 having reciprocating movement in a horizontal guide 85 477 carried by a frame arm or support 478 bolted or otherwise secured to a portion of the main frame. A link 479 is attached to the slide 476 and the upper end of an oscillating lever 480 is pivotally connected to the 90 said link and extends down and is fulcrumed at the lower end of an upright 481 as at 482. On the shaft 135 a cylindrical or bowl cam 483 is mounted and has a peripheral cam groove 484 therein which is engaged by a 95 roller 485 mounted on the oscillating lever 480 and by means of which the plunger 474 and its rod 475, through the medium of the slide 476, are given a proper reciprocation to discharge the inclosed packages of cigarettes 100 from the fixed pocket into the conveyer embodying the endless chain belt 463 having the throat links 464 and blades 465. The arm or support 478 is curved or has the contour of an elbow and provides means for 105 the application of a supplemental frame arm or support 486, said supplemental frame arm or support 486 being removably attached to the frame arm or support 478 and having a laterally curved or deflected upright member 110 487 provided with a slide seat 488 at its free end in which is mounted a slide 489 having a plunger rod 490 attached thereto and provided with a plunger comprising an attaching head 491 with a U-shaped plunger 115 member 492 attached thereto. The plunger as a whole, including the head 491 and member 492, is disposed at an oblique angle, as illustrated by Fig. 9^b, so as to accommodate the position of the throat links of the conveyer 463 that are disposed in alinement with the said plunger by the step by step movement of the conveyer comprising the belt 463, throat links 464 and blades 465. A link 493 is secured at one end to the slide 120 489, and to the opposite end of said link the upper end of an oscillating lever 494 is movably attached and extends downwardly and is fulcrumed to the upper terminal of the upright 481, as at 495, a portion of the said 130

lever 494 extending downwardly below the upper end of the upright 481 and inside of the latter and at its lower end the lever is provided with a roller 496 which engages a 5 suitable cam groove in the cylindrical or bowl cam 483 and whereby the lever 494, slide 489 and rod 490 and its plunger are given a reciprocation in timed relation to the movement of the endless belt 463 and its 10 throat links 464. The plunger rod 490 and its plunger, together with the operating parts therefor, are not used and are removed when a bander mechanism, which will be hereinafter explained, is operated in conjunction with the remaining parts of the 15 machine, and also when separately made cups are used, and when these latter cups are used the endless chain belt 463 conveys the packages introduced therein to a suitable 20 point of delivery. The packages discharged from the endless chain belt 463 and the throat links 464 thereof by the plunger rod 490 and its head are deposited in a tray 497 extending longitudinally with relation 25 to the bed of the machine, and the packages are moved gradually lengthwise of the said tray 497 by contact with each other and eventually are deposited in sequence on a carrier belt 498 moving under an outer reduced end 499 of the said tray and operated 30 by a shaft and pulley 500 to which power may be applied from a suitable source. The belt 498 may be of any length, and as shown by Fig. 8 it runs transversely over the bed of 35 the machine and is adapted to convey the packages which will be complete in accordance with a predetermined preparation of the inclosure or wrapper.

Figs. 44 to 54, inclusive, illustrate the application to bunches of cigarettes of various forms of wrappers, and the manner of folding these wrappers is also shown by these figures. Figs. 44 to 48, inclusive, particularly show the association of the cup and interliner and the operation of folding the same around the charge or bunch of cigarettes. The cup blank A, as shown by Fig. 1, is fed to the table 5 at the right end of the latter by an operator or may be applied thereto by any other means, and the successive blanks are taken up by the hooks 11 of the endless belts 10 and first fed under the pasting attachment and lined with paste at proper points as well as spotted through the medium of the devices hereinbefore described, and after passing the pasting attachment each cup blank moves inwardly until it arrives under the bridge attachment and then moves under the horizontally disposed feed plate 23. The interliner blank B, which is of greater width and less length than the cup blank, is fed from the roll 80 and at the same time severed and deposited upon the plate 23 of the bridge. The angular space member 25 extending along one

side edge of the plate 23 disposes the interliner blank B in such lateral position relatively to the cup blank fed under the bridge as to compensate for the difference in length of the two blanks and so that one end edge 70 of the interliner blank will coincide with the adjacent end edge of the cup blank, as clearly shown by Fig. 48 at a. Both blanks A and B are fed inwardly simultaneously by the hooks 11 when the latter reach the bridge and carry therewith the cup blanks, and owing to the angular inwardly projecting heads 12 the interliner blanks are always moved slightly in advance of the cup blanks and whereby the interliner blanks are 75 each projected at one edge beyond the adjacent edge of the cup blanks and the opposite edge of each interliner blank is slightly in advance of the adjacent edge of the cup blank, as shown by Fig. 48. As hereinbefore 80 indicated, the cup blanks are longer in one direction than the interliner blanks and when the interliner blanks are assembled with the cup blanks as just explained the one side of each cup blank projects beyond the 85 adjacent side of the interliner blank, as at b, see Fig. 48. The two blanks A and B are held in the relation just explained after the blanks both clear the bridge from under the latter and over the top of the same, and the two blanks remain in the positions in which they are arranged through the operation of each hook 11 and either pass under the coupon feeding attachment, as shown by Fig. 1, or if the introduction in the cigarette 90 package of the coupon is undesirable or is not effected then the two associated blanks pass onto the mounting rollers 117 and 118, the latter rollers being grooved as hereinbefore explained, to permit the hooks to 95 pass therethrough and the hooks continue to feed the associated pairs of blanks until a position immediately above the shaft 19 is reached, when the associated blanks will be engaged by the registering rollers 121 and 122, the main function of the latter rollers being to continue the inward feed of the associated blanks; and the upper roller 121 is grooved, as at 121^a, to clear the exposed 100 line of spots and paste on the cup blank, the paste causing the associated blanks to adhere after they leave the hooks. The associated blanks are projected inwardly under the bridge or guide 152 and are engaged by the delivery rollers 142 and 143, the upper delivery roller 143 being also grooved and reduced to clear the pasted portions of the cup blanks. In addition to the grooves in the uppermost roller 117 for the movement therethrough of the hooks 11, the roller 118 115 is also grooved to give clearance to the upper portion of the chain belt and hooks, and the said upper roller 117 also has paste clearing grooves therein. In other words, the rollers 117, 118, 121 and 143 will be pro- 120 125 130 135 140 145 150 155 160 165 170 175 180

vided with a reduced structure wherever necessary to clear the exposed pasted portions of the blanks moving thereunder in all forms of the blanks that may be used, whether embodying the cup blank and interliner or the simpler form of inclosures which will be hereinafter explained. The delivery rollers 142 and 143 dispose the associated blanks A and B on the table 144 over the opening 145, the coinciding edges of the blanks being moved into the groove 310, as shown by Fig. 17, the depth of said groove being just equal to the width of one side fold of the wrapper. When the combined wrapper, including the two blanks A and B, is fed onto the table 144 the edges of the blanks that are fed forward engage the stop flange 319, and by disposing a portion of the double blank in the groove 20 or slot 310 the said blank is held in place in proper relation to the opening 145 and the plunger 146 to accurately receive the charge of cigarettes to be disposed therein, and when the plunger 146 descends the supplemental bottom or follower 321 of the adjacent pocket 311 below will be elevated and occupy a position close to the under side of the cup blank, and when the said plunger 146 moves downwardly it pushes the charge of cigarettes into the interliner and at the same time the interliner and cup blank with the charge of cigarettes are forced downwardly against the supplemental bottom or follower 321 and the latter at this time will be free to move downwardly and then both the plunger 146 and the supplemental bottom of the pocket 311 will move together with the charge of cigarettes and the incomplete inclosure or wrapper until the supplemental bottom has reached the limit of its innermost movement, and at such time the portion of the combined wrapper or the interliner and cup that has occupied the groove or slot 310 will be completed as to its fold and form one side portion of the wrapper relatively to the charge of cigarettes, and consequently the charge of cigarettes in the pocket will be enclosed at opposite sides and at the bottom 50 within the pocket 311 with a greater portion of the wrapper projecting at the side of the pocket adjacent to the folding guard 360. When the mold wheel 312 rotates in the direction of the arrow the projecting portion of the wrapper or of the combined interliner and cup is pulled through the opening 145 of the table 144 and will be turned down over the top or outer portion of the charge of cigarettes by said guard 360 and a portion of the combined wrapper will project across the pocket 311. When the incompletely completed package is disposed in the pocket 311 the wrapper including the interliner and cup and the charge of cigarettes 65 will have the relative positions shown by Fig. 44, and when the mold wheel 312 rotates to bring an empty pocket 311 thereof into registration with the opening 145 for another charge and inclosure the immediately preceding charge or inclosure will have its wrapper folded inwardly by the guard 360, as shown by Fig. 45, and the wrapper will remain in the latter position until the incomplete package is discharged from the pocket 311 which it has occupied 70 into the fixed pocket, as hereinbefore explained, and when the package is discharged into this fixed pocket the opposite side fold of the wrapper will be completed, as shown by Fig. 46, and in such condition it will be 75 seen that the one end of the interliner will be very materially projected, as at C, and the adjacent cup edge will coincide with the adjacent ends of the cigarettes. The opposite ends of the incomplete package will be 80 open, and the cup portion of the wrapper will project outwardly beyond the interliner to the extent between the edges c and d as shown by Fig. 48. In accordance with the arrangement of the wrapper just explained, 85 when the end folds are made the interliner at one end of the package will be solely folded as it is the only projecting portion of the wrapper that can be folded. At the opposite end of the package the projecting portion of the cup is folded inwardly with the adjacent portion of the interliner for the reason that the cup at said end projects beyond the interliner, and the package will then appear as shown by Fig. 47. The fold 90 is effected through the medium, first, of the blades 443, then the blades 460, and finally through the medium of the blades 462, and in view of the preliminary application of paste to the cup member the parts of the 95 package will be securely fastened or will sufficiently adhere in their folded positions to render each package practical for commercial vendition. By this means it will be seen that a cup and interliner may be 100 simultaneously applied to a charge of cigarettes and the completed package will be discharged from the fixed pocket into the conveyor or endless belt 463 with its throats 105 464 and finally deposited on the tray 497 and 110 from the latter move onto the belt 498. It 115 will be understood from the foregoing description and as illustrated by Fig. 1, that the cup blanks are engaged by the shank portions of the hooks 11 below the heads 12, 120 the front edges 13 of the said heads, as shown particularly by Fig. 3, being straight and adapted to engage the rear edges of the interliners deposited on the plate 23 of the bridge. It is obvious that the projection 125 of the heads 12 relatively to the adjacent vertical edges of the hooks 11 may be varied and thereby the interliner blanks may be placed on the cup blanks beneath in varying positions or to modify the projection of 130

- one edge portion of each interliner blank beyond the cup blank as may be desired. In the form of feeding table shown by Fig. 2 the heads 12 of the hooks 11 do not operate 5 as feeding means, the blanks being engaged by the front or inner edges of the hooks 11 and the blanks are moved directly against the table 20, the form of feeding means for the wrappers or inclosures as shown by Fig. 10 2 being adapted for plain foil, glacine, plain or printed paper or other material, as hereinbefore stated, and this form of inclosure after it is applied to the charges of cigarettes is intended to be covered by a further 15 inclosure in the form of a cup which may have been previously formed by other mechanism and applied to the blades 466 carried by the throats 464 of the endless chain belt 463, or said cups may be applied 20 to the partially inclosed packages by other mechanism which will be hereinafter explained and forming an extension of the machine thus far described. In the form of feeding mechanism shown by Fig. 2 the 25 inner inclosure or the preliminary wrapper is fed from the roll 80 and cut off in suitable lengths by the mechanism hereinbefore particularly described and delivered on the plate 20 and then taken up regularly by the 30 hooks 11 and fed under the pasting attachment and then inwardly and may or may not be provided with a coupon, and finally the partial wrapper or inclosure of single thickness is delivered onto the table 144 over the 35 opening 145 under the plunger 146 in a manner similar to the combined cup and interliner above described. The charges of cigarettes are delivered into the partial wrappers as they are disposed on the table 40 144 and then the same operation is carried on with respect to the folding and shaping and pressing of the package as hereinbefore particularly specified, and the charges of cigarettes as thus inclosed are discharged 45 into the throats 464 of the endless chain belt 463 and into cups 466 that may be carried by the blades 465 and finally deposited on the tray 497 and from the latter delivered to the belt 498, or the partially inclosed 50 packages may be carried over to other mechanism which will be hereinafter explained. Figs. 49, 50, 51 and 52 clearly illustrate the manner of folding a single inclosure blank of whatever material desired around the 55 charge of cigarettes, and it will be seen that the operation of folding this blank is the same as that described in connection with the combined cup and interliner blank. The cup 466 is shown in detail by Fig. 53, and 60 the package as prepared and completed as illustrated by Fig. 52 may be inserted in the cup 466 and this doubly inclosed package may be vended as a complete package or submitted to further operations, as for instance the application of a band over the 65

outer exposed end of the inner inclosure for the cigarettes, as illustrated by Fig. 54. When a band is applied to the package as shown by Fig. 52, for instance, the treatment of the package and the securement thereon of the band will be somewhat different by the extension mechanism which will be hereinafter described, and after the band is applied the package will then be inserted in the cup, as shown by Fig. 54.

Instead of discharging the packages from the fixed pocket after the folding blades 443, 460 and 462 have operated to produce the end folds of the wrapper or inclosure, the improved machine is intended to be provided with an extension or an addition to accomplish various operations in connection with packages of cigarettes under certain conditions and especially to prolong the treatment of the packages sufficiently to permit the adhesive material to fully dry, and particularly before inserting the packages into previously or extraneously made cups, so as to overcome any tendency of the forward folded ends of the packages to open up during insertion into the cups; and when this extension or addition is used with the machine the conveyer embodying the endless belt 463 with the throats 464 and blades 465 and the coöperating mechanism is placed in operative association with the mechanism of the extension or addition, and the latter is mounted on the base of the machine and held in fixed position to receive the packages from the fixed pocket, and when this extension or addition is used the tray 497 and belt 498 will also be displaced and the mechanism for operating the endless belt 463 will be practically the same, only such changes in the application of the parts being made as are necessary to accommodate the particular arrangement of the endless belt. The same step by step movement of the endless belt and the parts connected thereto will ensue as in the arrangement hereinbefore described, and it is not to be understood that the mechanism that will now be explained is a modification of the previously described mechanism, but an extension or addition thereto for the purpose of subjecting the packages to further manipulation and also if desired to apply a band over the portion of the wrapper that directly incloses the charge of cigarettes and the subsequent insertion of the said banded inclosure in a cup. The bander mechanism, however, will not always be used, as means are provided for throwing the bander into or out of operation, and when the bander is not used the extension or additional mechanism will then be operated to further shape the packages and insert them in a cup instead of directly disposing them in cups from the fixed pocket where the end folds of the inclosure for the cigarettes are made. The extension or addi-

tional mechanism is mounted on the base 7 and the supplemental frame arm 486 together with the plunger rod 490 and its plunger and operating mechanism includ- 5 ing the lever 494 are detached. The plunger rod 475 with its plunger 474 and the support and operating means therefor are retained in position, as shown by Fig. 9^a, and provide means for discharging the packages from 10 the fixed pocket. When the extension or addition is used in connection with the remaining mechanism, the packages as discharged from the fixed pocket by the plunger 474 are pushed into a shuttle 501, as 15 shown particularly by Figs. 60, 61, 63 and 64, the said shuttle being mounted on a table or bed 502 having a slot 503 therein below the shuttle. The shuttle comprises upper and lower reversely arched members 504 and 20 505 having the contour and proportions as shown by Figs. 60 and 61, the two members 504 and 505 being practically half-sections of an inclosure with inner sides fully open to one another, and these members or sections 25 have an inside contour corresponding to that of a package of cigarettes pressed and shaped in the fixed pocket. The inner opposing side edges of the members 504 and 505 are normally spaced and the upper mem- 30 ber or section 504 is mounted to have yielding movement with relation to the lower member or section 505. At opposite sides of the lower member or section 505 are pairs of lugs 506, see Figs. 63 and 64, and secured 35 to these lugs are upwardly projecting U-shaped guide yokes 507, the said yokes 507 having lower outwardly projecting angular feet 508 and 509 at opposite sides, the foot 509 of each yoke being apertured and slotted, 40 as at 510, to receive a fastening screw 511, the said foot 509 being detachable from the screw 511 without wholly dissociating said screw from the lug 506 with which it is adapted to engage. The feet 509 of the 45 yokes 507 are in reverse positions relatively to the shuttle members, as shown by Fig. 59, and engaging each foot 508 is an upright pin 512 having a milled head 513 and a lower suitably screw-threaded extremity for 50 removably securing the parts, the pins 512 being extended upwardly as shown for convenience in reaching the same and manually detaching them from or attaching them to the feet 508 and lugs 506, and through the 55 medium of these pins and the yokes 507 when the screws 511 are loosened the upper member or section 504 may be readily removed from the lower section 505 of the shuttle or adjustment of the said member 60 504 relatively to the lower member 505 may be readily accomplished to overcome any irregularity of registration of the upper member relatively to the lower member. Each yoke 507 carries a pin 514 mounted in 65 the center thereof, the innermost yoke hav-

ing a central extension 515 in which its pin 514 is mounted. The lower ends of the pins 514 loosely project through openings 516 in the top of the upper member or section 504, and between the top of said member or section and the portions of the yokes above the same, springs 517 are mounted on the pins 514 so that the upper member or section 504 may have a vertically yielding action under spring tension. The lower member or section 505 has a rack 518 secured to the center of the bottom thereof exposed through the slot 503, the slot 503 being long enough to accommodate movement of the shuttle, and the lower or bottom portion of the member 30 or section 505 also has laterally projecting ribs 519 slidably mounted in grooves 520 in the upper portions of the side walls of the slot 503; and over the ribs 519 guide bars 521 are secured to hold the member 505 in 35 reciprocating association with relation to the bed 502. The complete shuttle is reciprocated or the upper member or section 504 regularly moves with the lower member or section 505. The operating mechanism for 40 the shuttle consists of a toothed segment 522 secured on a rock shaft 523 held by suitable pendant bearings 524 from the bed 502. On the shaft 523 a segment 525 is fixed and provided with a segmental head 526 having 45 slots 527 therein engaged by studs 528 projecting from the segment 522 and whereby a relative adjustment between the latter segment and the segment 525 may be made to modify the operation or throw of the segment 522. An elongated swinging segment 529 is held in continual mesh with the segment 525, the segment 529 being mounted on a fixed stub shaft 530 which is in the form of a pin engaging a bearing 531 depending 50 from a portion of the bed 502 in rear of the shaft 523, as clearly shown by Fig. 74. Below the plane and in rear of the shaft 523 a motion transmitting shaft 532 is mounted in suitable bearings, as at 533 and 534, also 55 depending from the bed or frame 502. The shaft 523 carries among other instrumentalities a cam 535 having a suitable cam groove 536 therein which is engaged by a roller 537 attached to the segment 529. 60 Through the medium of the cam groove 536 the segment 529 is regularly associated to impart a rocking motion to the shaft 523 through the segment 525, and in turn the segment 522 is similarly operated to actuate 65 the rack bar 518 and thereby reciprocate the shuttle comprising the members 504 and 505. The shaft 532 has a beveled pinion 538 thereon which meshes with a pinion 539 on a counter-shaft 540 also held in suitable 70 bearings depending from the bed or frame 502. The shaft 540 also has a sprocket wheel 541 thereon engaged by a chain belt 542 which is also trained over a sprocket 543 on the shaft 135, and by this means motion 75

is transmitted from the main driving element of the mechanism to the shaft 532 and in turn the latter actuates the rock shaft 523 by the interposed mechanism just explained.

5 Rising from the bed 502 at one side of the shuttle are supporting arms 544 and 545 having bearings 546 and 546^a at their upper ends. In the bearing 546 of the arm 544 a short rock shaft 547 is mounted, and below 10 the said bearing and rock shaft is a longer rock shaft 547^a rotatably held by the bearing 546^a and projecting under the shaft 547 above. On the short rock shaft 547 an arm 549 is mounted to swing or oscillate and has 15 a folding blade 550 at its lower end. The longer rock shaft 547^a has a crank arm 548 secured thereto and depending below the same and on the said rock shaft 547^a a shank 551 is mounted to swing or oscillate 20 and carries a folding blade 552 at its lower end which acts with the blade 550, both of the latter blades being movable closely over the inlet end of the shuttle 501. On the rock shaft 547^a in rear of the bearing 546^a a shank 25 551^a is mounted to oscillate and has a lower blade 552^a which is movable across the outlet end of the shuttle. The shanks 551 and 551^a and their respective blades 552 and 552^a are simultaneously operative to move 30 inwardly and outwardly and the shank 549 and its blade 550 is operative from the rock shaft 547^a through the medium of the toothed segment 553 connected to said shank extremity engaging the rock shaft 547, the 35 segment 553 being held in continual mesh with a similar segment 554 connected to the extremity of the shank 551 mounted on the shaft 547^a. The crank arm 548 is secured to the shaft 547^a by means of a sleeve 555 40 forming a part thereof, and attached to the lower end of the crank arm 548 is a connecting rod 556 which is suitably bent to clear the mechanism below and has an outer forked end 557 to slide over a band feed controlling shaft 558 mounted in suitable bearings at one side of the bed 502, the forked end 557 having a spring 559 secured thereto and to one side of a bifurcated reel frame 560 also held by a suitable supporting means outwardly beyond the shaft 558 and which may 45 be a part of the bed or main frame of the machine, as indicated by dotted lines in Fig. 56. The spring 559 insures a resistance to inward movement of the rod 556 and retention of the forked end 557 of said rod with 50 relation to the shaft and also a positive engagement of a roller 561 carried by the rod 556 adjacent to the forked end 557 and in continual contact with the periphery of a cam 562 mounted on the shaft 558, as shown 55 by Figs. 55 and 57. Through the medium of the mechanism just described the shanks 549, 551 and 551^a with their blades 550, 552 and 552^a are regularly moved inwardly and 60 outwardly with relation to the opposite ends 65

of the shuttle, and the movements of these blades are in timed relation to the remaining mechanism whereby the packages are inserted in and discharged from the shuttle.

The rear extremities of the members 504 and 505 of the shuttle 501 are transversely slotted, as at 563, see Fig. 61, for movement therethrough and clearance of a band when the banding mechanism is used or brought into service and which will be more fully 70 hereinafter explained. Rising vertically from the bed 502 at opposite sides of the rear extremity of the shuttle 501 are two upright loosely mounted rollers 564 having central enlargements or increased in diameter at the center, as at 565, for engagement with the band when the latter is applied to the packages; and in rear of these rollers 564 is a chute 566 having the front side wall cut away adjacent to the rollers 80 564, as at 567, to provide an inlet to the said chute, the rear or inner end of the shuttle 501 being closely associated with said inlet at the terminal of its innermost stroke when the discharge of the successive packages ensues therefrom. Directly opposite the inlet or cut away portion 567 of the chute 566 a gate 568 is located and has a spring hinge connection 569, as shown by Fig. 57, the object of said gate being to clear 90 the adjacent ends of the packages so as to rearrange the folds and see that the latter are properly secured prior to the discharge of the packages from the chute. The gate 568 is normally closed through the action 100 of the spring hinge therefor, but may be readily operated to open the same for the purpose specified. The chute 566 has attaching brackets 570 and 571 connected to the opposite side walls thereof and forming 105 attaching means for the latter, said brackets having slots 572 for adjustable engagement with relation to screws or other fastenings 573 and whereby the side walls of the chute may be shifted if desired and also conveniently applied on the bed 502. The outer end of the chute 566 is in the form of an upright end wall 574, openings 575 being formed in the side walls of the chute in transverse alignment adjacent to the outer 115 end wall 574 to facilitate the discharge of the packages and the movement transversely through the outer end of the chute of a discharge plunger 576 supported by a slide 577 movable in guide grooves 578 in the under 120 adjacent portion of the bed 502, the slide having a rack 579 depending therefrom and engaged and operated by a pinion 580 mounted on a stub shaft 581 rotatably disposed in suitable bearing means held by a 125 part of the under frame or projecting from a bracket 582, as shown by Fig. 74. On the shaft 581 is a smaller pinion 583 which is maintained in continual mesh with a toothed segment 584 secured to the shaft 523 and 130

operated regularly by the latter in timed relation to the movements of the shuttle. The packages are regularly fed outwardly through the chute 566 in sidewise engagement, a number of the packages occupying the chute at the same time, and over this chute is a cover 585 which has its outer end connected to the end wall by a spring hinge, as at 586, see Fig. 55. The inner end of the cover 585 is free, and to support the cover in a positive horizontal plane bearing stops 587 are secured to opposite sides of an intermediate portion thereof to contact with the upper edges of the side walls of the chute 566, and between the bearing stops 587 a post or pin 588 is secured to the said cover and whereby the latter may be raised and lowered to expose the packages moving through the chute 566 for any purpose desired. The cover 585 is held down in closed position by the action of the spring 586 and therefore exerts a yielding pressure on the upper edges of the packages moving through the chute. The inner end of the chute 566 adjacent to the gate 568 is fully open, and as hereinbefore indicated the packages are delivered into the chute by endwise movement from the shuttle 501, thereby bringing the sides of the packages against each other when moving through the said chute 566. The packages are shifted through the chute by a step by step feed through the medium of a plunger or expeller 589 having a shank 590 movable in guides 591 on the bed 502. The base of the plunger 589, as shown by Fig. 61, has a groove 592 extending thereacross and likewise the one wall, at least, of the chute 566 has an intermediately located longitudinal groove 593, these two grooves giving a clearance to bands when the latter are applied to the packages without crowding the said bands into the packages when the latter are shifted through the chute 566. The shank 590 of the plunger 589 is secured to a slide 590^a and the latter is mounted to move over a slot 594 in the bed 502 and has an arm 595 depending therefrom through the slot and carrying a horizontally disposed roller 596 at its lower end which engages a peripheral cam groove 597 in a cylindrical cam 598 secured on the shaft 532. The cam groove 597 is of such contour as to impart a proper and timed reciprocation to the plunger 589 and its shank 590 relatively to the discharge of the packages from the shuttle. The packages are individually discharged or expelled from the chute 566 into a conveyer embodying an endless chain and throat links as hereinbefore described, and then liberated from the said conveyer or carrier onto the tray or chute therefor. In other words, the same operation of inserting the packages in the cups held by the conveyer or carrier is carried out when this extension or additional mechanism

is used as in the arrangement of the machine first described. The additional mechanism as thus far described may be used alone without any additional treatment or manipulation of the packages, and as the 70 packages are discharged from the fixed pocket the shuttle 501 occupies the position shown by Fig. 64, the insertion of the successive packages in the shuttle effecting a shifting movement of the packages there- 75 through and a successive discharge of the said packages from the shuttle by the packages themselves. After each package is inserted in the shuttle the latter moves inward to the position shown by Fig. 63 and 80 simultaneously the two blades 550 and 552 move over the inlet or front end of the shuttle and close the exposed end folds of the adjacent package and at the same time the inner or rear blade 552^a closes over the 85 rear end of the shuttle and engages the folds at the end of the package exposed at said shuttle rear end, the position of these blades being clearly shown by Fig. 63. The blades then open and clear the end of the shuttle 90 and the latter then moves outwardly, as shown by Fig. 64, the shuttle when filled carrying two packages, and upon the insertion of the third package the innermost package is pushed out in an endwise direc- 95 tion between the rollers 564, the shuttle at such time having been moved its full extent inwardly in the position shown by Fig. 59 so as to discharge each package fully within the chute 566. The movements of 100 the shuttle just explained are accomplished through the contour of the cam groove 536, as shown by Fig. 61, and it will be understood that the normal position of the shuttle containing two packages and when engaged 105 by the blades is shown by Fig. 63, the shuttle immediately subsequent to the position it assumes as shown by Fig. 63 being moved outwardly to receive a third package and expel the innermost package as illustrated by Fig. 110 64, and from this latter position the shuttle moves inwardly again and finally moves rearwardly toward the chute 566 to the full limit of its stroke. After the packages have been delivered to and discharged from the 115 shuttle and successively disposed in the chute 566 they will have been completely shaped and the ends will be positively secured and the several packages as a consequence will be in proper condition for insertion into a cup, or if a cup is not used they may be delivered from this addition or extension and conveyed to any suitable place of deposit or final discharge.

The extension or additional mechanism in- 125 cludes a banding mechanism which may or may not be used, but when it is thrown into operative relation bands are regularly applied over the ends and portions of the opposite sides of the packages as they are dis- 130

charged or forced out if the shuttle 501 into the chute 566. The operation of this banding mechanism is accomplished through and in timed relation to the actuation of the 5 plunger 589 and its shank 590 so that a portion of a band 599 is fed across the rear or inner extremity of the shuttle 501 through the slots or openings 563 and close to the intermediate enlarged portions 565 of the 10 rollers 564, this band being separated in regular lengths by means which will be presently explained. On the shank 590 of the plunger 589 a rack bar 600 is secured and engages a pinion 601 held suspended on the 15 lower end of a vertical shaft 602 supported by a goose-neck 603 secured to an adjacent portion of the bed 502 and projecting upwardly and in part horizontally over the said shank 590 of the plunger 589. The 20 goose-neck carries suitable bearings 604 and 605, the shaft 602 being mounted in the bearing 604, and on this shaft 602 immediately above the pinion 601 a sleeve 606 is mounted and has an upper flange 607 for the 25 support of clutch mechanism. The sleeve 606 is secured to the shaft 602 to rotate therewith, and the clutch mechanism consists essentially of a clutch member 608 loose on the shaft, but secured to the sleeve 606 by a plurality of pins 609. This clutch member consists of a plate having a plurality of approximately radial shoulders 610 continuing into straight walls 611 tangential to the shaft 602, and adjacent to the intersection of the 30 shoulders 610 and the said wall 611, sockets 612 are formed to receive springs 613. The shoulders 610 are curved at their points of intersection with the straight tangential walls 611, as at 614, to receive portions of 35 cylindrical friction devices 615 which have a yielding engagement with the springs 613, each shoulder 610 and the wall 611 continuous therewith being formed by cutting the member 608, which has originally the contour of a circular disk, at proper angles and 40 boring the member from the shoulders inwardly into the body of the disk to provide the sockets 612 for the springs 613. In the bearing 604 and surrounding the shaft 602 45 is an elongated sleeve 616 which has a hollow gear 617 on its lower end fitting over the clutch member 608 and bearing upon the flange 607, the latter serving as a table conjointly with the upper portion of the sleeve 50 616 from which it projects as a support for the clutch member and the said gear. The upper side of the gear 617 bears against the lower end of the bearing 604, and the sleeve 616 extends above the upper end of said 55 bearing, and thereover a space collar 618 is secured and engages the upper end of the bearing 604. The upper end of the shaft 602 is also provided with a set collar 619 which bears upon the upper end of the sleeve 60 616 and a portion of the collar 618. In one

direction of movement of the shaft 602 the clutch member 608 is shifted or rotates partially with the shaft to set up a binding action between the cylindrical friction devices 615 and the inner wall of the hollow 70 gear 617 so that the said gear will regularly rotate with the shaft. The reverse movement of the shaft 602, however, will not set up a binding action through the member 608 and the cylindrical friction devices 615 for 75 the reason that the said member 608 will not have a rotation imparted thereto in a direction that would set up a binding action by the tangential walls 611 on the devices 615 and the inner wall of the gear, and hence 80 the said gear will not be rotated. The rotation of the pinion 601, shaft 602 and gear 617 through the clutch mechanism just described will ensue when the plunger 589 and its shank 590 move outwardly to force the 85 packages lengthwise through the chute 566, the stroke of the plunger 589 and its shank 590 being such as to move the packages in the chute 566 a distance approximately equal to the thickness of each package so that 90 there will be a clearance at the inner terminal of the chute when the plunger 589 returns to normal position for the reception of another package from the shuttle 501. When the plunger 589 moves outwardly to 95 shift the packages in the chute 566, the gear 617 is rotated to actuate the band feeding mechanism which will now be described, the actuation of said band feeding mechanism causing the band 599 to be regularly disposed across the rear end of the shuttle 501. In the bearing 605 a shaft or spindle 620 is mounted and has a lower enlargement 621 forming a shoulder which engages the lower 100 end of the said bearing. The lower end of the shaft or spindle 620 is formed with a flange 622 and the upper end is screw-threaded to receive a nut 623 for holding the said shaft or spindle up in place in the bearing 605 and also to operatively associate 105 the said shaft or spindle with the bearing. On the lower enlarged portion 621 of the shaft or spindle 620 a feed wheel or disk 624 is mounted to rotate and has a circumferential groove 625 formed therein and also 110 provided with an integral sleeve 626 which extends upwardly to the lower end of the bearing 605 and is reduced, as at 627, to receive a gear ring 628 which is secured thereon by screws 629, the said gear ring 115 being practically a part of the feed wheel or disk 624 and held in mesh with the gear 617. The feed wheel or disk 624 is always held in a positive position by bearing on the flange 622 at the lower end of the shaft 120 or spindle 620, and the lower side of the said wheel or disk 624 slightly projects over the top of a moistening tank or receptacle 630 having a top cover 631 with a slot or opening 632 therein adjacent to the said 125 130

wheel or disk 624. The slot or opening 632 is essentially of keyhole contour or has an enlarged portion, as at 633, into which a reduced extension 634 fully opens. The moistening tank or receptacle 630 is secured on the bed 502, and as shown by Figs. 70 and 71 an elongated shiftable plate 635 is fulcrumed, as at 636, within the said tank or receptacle and is centrally arched as at 637 where it engages its fulcrum to give it a working clearance and to provide for the depression of the opposite ends 638 and 639 which are movable over the bottom of the tank. The end 638 of the plate 635 has a spring 640 attached thereto and to a pin 641 extending upwardly from the bottom of the tank or receptacle, said spring offering a resistance to the movement of the plate or support 635. Secured to the end 639 of the plate or support 635 is a vertical shaft or spindle 642, as clearly shown by Fig. 68, and loosely mounted on the said spindle is a gear 643 which is held in continual mesh with the gear ring 628 and has an elongated sleeve 644 which extends downwardly to the lower terminal of the shaft or spindle 642 to the end 637 of the plate or support 635. On the sleeve 644 a cylinder 645 of absorbent material, such as felt, is mounted and so secured to the sleeve as to rotate therewith and also with the gear 643. The absorbent cylinder or sheathing 645 extends through the opening 632 in the top or cover 631 of the tank or receptacle 630 and continually dips into the water or other moistening liquid in the tank or receptacle, the entire cylinder 645 being supplied with moisture by capillary attraction. Owing to the fulcrum plate or support 635 carrying the shaft or spindle 642, the latter together with the gear 643 and absorbent cylinder 645 may be shifted or adjusted to throw the same into engagement with the wheel or disk 624 or away from the latter, and as shown by Fig. 68 the band 599 engages the groove of the wheel or disk 624 and is held thereby in close engagement with the cylinder 645 when the latter with its shaft or spindle 642 is adjusted to set up contact between the said wheel or disk and the cylinder. The spring 640 connected to the end 638 of the plate or support 635 tends to maintain an engagement of the absorbent cylinder 645 with the wheel or disk 624, and when the plate or support 635 is adjusted to disengage the cylinder 645 from the wheel or disk 624 and the gear 643 from the gear ring 628 the said spring 640 is distended. The plate or support 635 is held on its fulcrum 636 by a bearing sleeve 646 which is engaged by a clamping screw 647 which also serves as the means for connecting the plate or support 635 and the axis on which the said plate or support is adapted to swing during its adjustment. The upper end of the shaft or

spindle 642 is reduced and formed as a screw-threaded stem 648, and thereon an adjusting post or pin 649 is secured and has an upper terminal head 650 of such length that it may be readily grasped by an operator to throw the absorbent cylinder 645 and the said shaft or spindle 642 into and out of working position relatively to the wheel or disk 624. The enlarged portion 633 of the opening 632 in the cover 631 of the tank or receptacle 630 is large enough to compensate for a maximum adjustment of the shaft or spindle 642 and the parts carried thereby, and the reduced portion 634 of this opening may be conveniently used as an ingress means for the water or other liquid that is disposed in the tank or receptacle 630. To insure an ample quantity of liquid around the lower extremity of the absorbent cylinder 645 the bottom of the tank or receptacle 630 is inclined inwardly toward the said lower extremity of the absorbent cylinder 645, as at 651, see Fig. 71, and by this means a continual drain toward the lower end of the absorbent cylinder 645 is maintained. Between the nut 623 and the upper end of the bearing 605 an adjusting cam plate 652 is pivotally mounted and formed with a cam edge 653 which continues into an abrupt angular edge 654 terminating in a projecting shouldered stop 655. To operate this adjusting cam plate a pin or stud 656 projects upwardly therefrom adjacent to the inner straight edge thereof. When the absorbent cylinder 645 is in engagement with the grooved wheel or disk 624 and the gear 643 meshes with the gear ring 628, the plate 652 will occupy the position shown by Figs. 55 and 66, and when it is desired to effect a release or disengagement of the absorbent cylinder 645, the shaft or spindle 642 and gear 643 relatively to the wheel or disk 624 and the gear ring 628, the cam plate 652 is pulled around to cause the cam edge 653, which is in continual engagement with the post or pin 649, to move over the latter and gradually force the said post or pin and the shaft or spindle 642 together with the parts carried thereby outwardly in the opening or slot 632 of the cover 631 of the tank or receptacle 630, and when the edge 654 of this cam plate is reached and the shouldered stop 655 engages the post or pin 649 the disengagement of the cylinder 645 and the gear 643 relatively to the wheel or disk 624 and gear ring 628 will be complete, and the shaft or spindle 642 together with the parts just mentioned and carried thereby will be held against accidental movement in view of the fact that the edge portion of the cam plate 652 then engaging the post or pin 649 will be past the fulcrum point of the said plate and the shaft or spindle 642 with the parts carried thereby will be held in this disengaged position against the resisting action 130

of the spring 640. When an engagement of the cylinder 645 and the wheel or disk 624 as well as the gear 643 and gear ring 628 is desired, the cam plate 652 is moved rearwardly or in the opposite direction and the spring 640 gradually draws on the plate or support 635 and places the parts in the position particularly shown by Figs. 66, 67, 68 and 69. Therefore, at any time desired the 10 banding mechanism or the feed of the band 599 may be caused to cease operation and under such conditions the packages may be treated or operated upon by the extension or additional mechanism without the function 15 of the banding mechanism or attachment. The band 599 is severed in predetermined lengths at intervals in accordance with the feed thereof and the length desired to be applied to the end of each package. The 20 band is closely held between the wheel or disk 624 and the cylinder 645 when the latter is in engagement with the wheel, as clearly shown by Fig. 68, and the adhesive material that may be on the band is moistened 25 by the liquid in the tank or receptacle 630, or in some instances this tank or receptacle might be the paste supplying tank or receptacle, but it is preferred that the band be originally prepared with adhesive material 30 on one side and moistened through the medium of the cylinder 645. The severing or shearing means is located adjacent to the point of engagement of the cylinder 645 with the grooved wheel or disk 624 and between 35 the latter devices and the rear end of the shuttle 501 and comprises a bracket 657 secured to the bed 502 and having an upper angular extremity 658 which constitutes a combined guide and shearing die and is provided 40 with a groove 659 through which the band has movement, the inner end edge of the extremity 658 being constructed and shaped to form a die or shearing member 660, as clearly shown by Fig. 66. The band 599 is loosely held in position in the groove 659 by an upwardly projecting spring keeper 661, as shown by Fig. 67, to prevent displacement of the band or to hold the latter in positive position in this portion of the 50 shearing or cutting organization for operation therewith of a movable cutting or shearing blade 662 provided with an upper angular cutting or shearing member 663 with an inclined edge 664 which moves in close relation to the die 660 and operates to sever or cut the band projected through the die or moving in the groove 659. The band 599 is fed outwardly from the angular extremity 658 through the groove 659 therein and beyond 55 the die 660 against the rollers 564, and after passing the said rollers enters a suitably recessed stop 665 secured on the bed 502 adjacent to the outermost roller 654, as shown by Fig. 66, the said stop 665 limiting the feed of the band and so positioned

that when the end of the band is engaged therein a sufficient length of the band will be projected outwardly beyond the end of the shuttle and the ends of the packages coming through the latter to engage the adjacent side of each package a sufficient distance or in accordance with the extent of the end of the band over the package sides as may be predetermined. The same length of band relatively to the opposite sides of the packages exists between the cutting or shearing devices and the inner roller 564, and by this means the band will be applied over the opposite sides of each package an equal distance. The movable shearing blade 662 is carried on the upper end of an oscillating arm 666 extending through a slot 667 in the bed 502, the said arm being fulcrumed on a hanger 668 depending from the under side of the bed and having a roller 669 at its lower end which is held in constant engagement with a cam disk 670 also mounted on the shaft 523 and having a peripheral cam enlargement 671, the roller 669 being held in contact with the peripheral edge of the cam disk 670 by a spring 672 secured to the oscillating arm or lever 666 and also to an adjacent portion of the bed or frame. As the cam disk 670 rotates and the cam enlargement 671 is brought into engagement with the roller 669 the arm or lever 666 is oscillated or caused to move gradually over the fixed die 660 against the resistance of the spring 672 and sever the band, and after the cam enlargement 671 is passed or has become disengaged from the roller 669 the arm or lever 666 resumes its normal position as shown by Fig. 67. The severing of the band 599 in predetermined lengths is effected at regular intervals and in timed relation to the movements of the shuttle 501 and also relatively to the forward and return strokes of the plunger 589. The gear 617 carried by the sleeve 616 is restrained in its rotation or prevented from having too loose movement by a brake means which will now be described. In the rear portion of the bearing 604 an opening 673 is formed to expose a portion of the sleeve 616, and held in tight frictional engagement with the said sleeve 616 is a brake or pressure head 674 carried at the free end of a spring arm 675 which has its opposite end curved partially around and secured to the bearing 605. To regulate the pressure of the head 674 against the sleeve 616 an adjusting screw 676 engages the spring arm 675 and also the web 677 between the bearings 604 and 605, all as clearly shown by Fig. 72. Above the shaft 558 and mounted in suitable bearings supported by the adjacent bed or frame is a shaft 678 on which a feed disk 679 is mounted to freely rotate, and on the said shaft 558 is a companion positively driven feed disk 680. The shaft 558 is driven by a 130

sprocket wheel 681 over which a chain belt 682 is trained and also over a sprocket wheel 683 mounted on a motion transmitting shaft 684 supported in a suitable bearing on a 5 pillar or post 685 and also carrying a larger sprocket wheel 686 which receives motion from the chain belt 542 which actuates the shaft 540 to rotate the shaft 532 through the beveled gears 538 and 539. The sprocket 10 wheel 686 is located in proximity to the sprocket wheel 543 so that the chain belt 542 may practically serve as the operating means for both sprocket wheels 686 and 543. The feed disks 679 and 680 are shown in detail 15 by Fig. 73, the feed disk 680 having a peripheral groove 687 with a boss or ridge 688 to set up an interval feed of the band 599. The feed disk 679 has its periphery partially covered by a circumferential friction band 689 of rubber or other analogous material, and this disk 679 is of such diameter and the shaft 678 at such distance 20 from the shaft 558 that the periphery of the said disk 679 projects into the groove 687 of the disk 680, but the only contact between the two disks is effected when the boss or ridge 688 comes around into engagement with the friction band 689 of the disk 679, and during this contact of the ridge 688 25 with the friction band 689 a firm biting engagement with relation to the band 599 is set up and the latter is fed a distance equal to the length of the ridge 688 and which will be just the length of the band desired for 30 application over the end of each package. The band 599 is fed from a reel 690 removably mounted in the reel frame 560 and passed between the disks 679 and 680, as shown by Fig. 56. From the two disks 679 35 and 680 the band 599 passes over and engages the upper portion of the shaft 335 which carries the mold wheel 312 and the Geneva plate 336, and from the said shaft 335 the band passes under a horizontally 40 disposed direction roller 691 mounted in a suitable bearing bracket 692 held on the bed 502. From the roller 691 the band then continues inwardly over a vertically disposed grooved direction roller 693 which 45 disposes the said band in vertical position, and from the roller 693 the band is carried between the absorbent cylinder 645 and the feed roller or disk 624 and then onto the cutting or shearing mechanism hereinbefore 50 described. It will be seen that the band has a step by step feed motion imparted thereto by the disks 679 and 680 and is always maintained in taut condition so as to 55 avoid a surplus supply thereof and preserve 60 a positive length which is severed for application to the end of each package. After the band 599 has been brought into engagement with the rollers 564 and held in position, as particularly shown by Fig. 66, 65 the moistened side of the band is next to

the end of each package delivered from the shuttle 501, and as the packages are successively pushed outwardly or discharged from the shuttle the ends thereof engage the intermediate portion of the band between the 70 rollers 564 and the movement of the packages across into the chute 566 causes the bands to be regularly applied to the forward ends of the packages in view of the fact that the latter pass between the rollers 75 564 and said rollers turn the portions of the band projecting beyond the opposite sides of each package against the said package sides, the rollers 564 being spaced apart just a distance equal to the thickness of each 80 package and the portions of the band which are applied against opposite sides of the package so as to insure a positive adhesion of the band to the package and a movement of the latter with the band thereon between 85 the rollers without undue pressure or inward forcing of the portion of the band on the sides of the package into the latter.

The entire mechanism embodied in the extension or addition may be cut out without stopping the actuation of the remaining mechanism by means which will now be described. On the shaft 135 a lock cam 694 is keyed adjacent to a disk 695 having a sleeve 696 secured on an elongated hub 697 of the 95 sprocket wheel 543, the hub 697 with its sprocket wheel being normally loose on the shaft 135. The disk 695 carries on the face adjacent to the locking cam 694 an intermediate fulcrumed clutch lever 698 which 100 has a hooked or shouldered end 699 to engage a notch 700 in the cam 694, all as clearly shown by Figs. 75 and 76. The clutch lever 698 adjacent to the upper shouldered or hooked end 699 thereof has a pin 105 701 secured thereto and movable through a slot 702 in the disk 695, and to this pin a spring 703 is secured and also to the side of the disk 695 opposite that on which the lever 698 is applied. The opposite extremity of the clutch lever 698 is formed with a contact tail 704 having an outer slightly concaved edge 705 merging into the outer convex edge 706 of the lever. Below the shaft 135 in a bearing bracket 707 secured 110 to the base 7 a shifting shaft 708 is mounted and carries a disk or circular head 709 which is adapted to be moved into contacting position relatively to the tail 704 of the lever 698. The end of the shaft 708 opposite that 115 having the disk or head 709 thereon is provided with space flanges 710 to form a groove 711 to receive the forked end 712 of a shifting lever 713 fulcrumed as at 714 on the base or bed 7 and projecting outwardly 120 to one side of the bed for convenience in moving the shaft 708 and throwing the head or disk 709 into and out of operative position relatively to the tail 704 of the clutch lever 698. When the shaft 708 is shifted to 125 130

bring the head or disk 709 into position for engagement with the tail 704 of the lever 698, the tail of the lever upon engaging the head causes the hooked or shouldered end 699 of the lever to be thrown out from the notch 700 of the locking cam 694 against the resistance of the spring 703, as shown by Fig. 76, and while the lever 698 is thus disengaged from the locking cam 694 the 10 sprocket wheel 543 is released from the said shaft 135 and as a consequence all of the mechanism of the addition or extension of the machine is rendered inoperative and the shaft 135 will continue to rotate and actuate 15 the remaining mechanism of the machine. This operation of releasing the sprocket wheel 543 from the shaft 135 and stopping the action of the mechanism of the addition or extension may be effected at any time 20 desired or found necessary. Likewise the entire machine, including all the mechanisms that have been described, may be controlled as to its operation through the means for applying power to the shaft 135, 25 which consists of a band wheel 715 and clutch members 716 and 717, the clutch member 716 having a lever 718 engaging the same and fulcrumed as at 719 to a bracket 720 held on an adjacent part of the bed or base 7. To the lever 718 an operating rod 721 is secured and extends forwardly under the rear portion of the machine and has an operating lever 722 attached thereto and extending outwardly within easy reaching distance 30 at the rear side of the machine, as shown by Fig. 8. The extension or addition mechanism when operatively cut off may be quickly set in operation by shifting the shaft 708 with its head or disk 709 out 35 of engagement with the tail 704 of the clutch lever 698, and the notch 700 in the locking cam 694 will be engaged by the shouldered or hooked end 699 of the lever 698 when the said notch arrives opposite 40 the said end of the lever, and during the time that the shouldered or hooked end 699 of the lever is out of engagement with relation to the locking cam after the lever has been released for engagement with said 45 cam and before the notch 700 arrives in position to receive the shouldered or hooked end 699 of the lever, the latter end will bear and ride upon the periphery of the said cam 694 owing to the fact that the spring 703 50 will immediately come into play as soon as the tail 704 is released. The extension or addition mechanism is also provided with means for manually operating the same for any purpose that may be desired, such as 55 to properly position the shuttle at the start of the operation of the extension mechanism, said manually operative mechanism consisting of a fixed spindle 723 secured to an under portion of the bed, as shown by 60 Fig. 74, and having an elongated sleeve 724 65

rotatably mounted thereon and carrying a gear 725 at its inner end which is adapted to be moved into engagement with a gear 726 on the adjacent end of the shaft 532. The sleeve 724 has a hand wheel 727 fixed 70 thereto whereby the said sleeve and its gear 725 may be rotated on the fixed spindle 723. The sleeve 724 with its gear and the hand wheel 727 are prevented from moving outwardly beyond a predetermined distance on 75 the spindle 723 by a stop washer or collar 728 held in place by a nut 729 engaging the outer screw-threaded end of said spindle 723. It will be understood that the sleeve 724 with its gear 725 may be pushed inwardly until full mesh between the gears 725 and 726 is effected, and the shaft 532 may then be rotated in either right or left directions by correspondingly rotating the hand wheel 727, and after the mechanism 80 has been arranged as desired the hand wheel 727, sleeve 724 and gear 725 may be drawn outwardly on the spindle 723 to disengage the said gear 725 from the said gear 726. The improved machine hereinbefore disclosed also embodies heating means that may be used when found desirable for sealing portions of the folds of the wrappers. When the heating means is used the banding attachment will be adjusted or manipulated 85 to render the same inactive, and the material used for the wrappers will consist of wax paper or other analogous paper having material applied thereto which will melt or partially melt under the action of heat and 90 form an adhesive between parts of the wrapper or wrapper folds. The improved heating means is located in the discharge chute 566 which receives the packages having the wrappers folded, but loose or unsealed, and said heating means in the present instance is of an electrical type. The opposite sides or walls of the chute 566 are formed with elongated recesses 730, and in each of these recesses, which are located at 95 100 the inner portions of the sides or walls of the chute, a suitably insulated heating plate 731 is mounted and is provided with outwardly projecting connecting posts or plugs 732 for attachment of electrical terminals 105 thereto and which may lead from a suitable source of electrical generation. The heating plates 731 are located nearer the inlet end of the chute 566 and terminate some 110 distance from the delivery end of said chute 115 so that the packages passing through the chute and operated upon by the said heating plates will have time to cool or the portions of the wrapper which have been affected by the heating plates will sufficiently adhere before the packages are discharged from the 120 said chute 566. The heating plates 731 may be of any preferred type and are positively held against movement into the recesses 730, 125 the inner surfaces of the plates being flush 130

with the inner surfaces of the sides or walls of the chute 566 so that there may be no obstruction to the free passage of the packages from the chute toward the discharge outlet of the latter. By this means packages may be quickly and effectively sealed, and it will be understood that in view of the disposition of the packages in the chute 566 from the shuttle the folded ends will pass close to or in engagement with the plates 731 and thereby become heated sufficiently to melt or soften the wax or other material carried by the wrapper, and after these ends of the wrapper so treated have passed the plates they will gradually cool and at the same time will be pressed tight and adhere to the adjacent portions of the folded ends of the wrappers. This mode of sealing the wrapper of a cigarette package will be found advantageous and economical, and said sealing operation may be carried on without in the least affecting the cigarettes inclosed by the wrappers.

What is claimed is:

25 1. In a cigarette packaging machine, the combination of means for feeding an inclosing wrapper to a predetermined point, preliminarily compressing and disposing a specific number of cigarettes in the wrapper, molding means into which the wrapper and cigarettes are pressed, and compressing, shaping and wrapper folding means to which the wrapper and cigarettes from the molding means are discharged.

35 2. In a cigarette packaging machine, a table over which inclosing means is fed, the table having a discharge opening over which the inclosing means is disposed, means for preliminarily compressing and delivering a specified number of cigarettes on the inclosing means, a molding means into which the cigarettes and inclosing means are discharged through the said opening, the inclosing means being partially folded while in the molding means, and means for compressing, shaping and effecting a positive closure of the inclosing means at opposite ends of the package.

3. In a cigarette packaging machine, means for feeding an inclosure to a predetermined point, mechanism for bunching a predetermined number of cigarettes and compressing and disposing them over the inclosure, a movable molding means into which the cigarettes and inclosure are simultaneously pressed, the inclosure being partially folded over the bunch of cigarettes in the molding means and during the movement of the latter, and compressing, shaping and folding mechanism to which the inclosure carrying the cigarettes is discharged.

4. In a cigarette packaging machine, the combination of means for feeding an inclosure to a predetermined point, means for separating and compressing and disposing a

charge of cigarettes of a specified number over the inclosure, a movable molding means into which the inclosure and cigarettes are pressed, the inclosure being partially folded by the molding means and during the movement of the latter, and compressing, shaping and molding mechanism to which the inclosure and cigarettes from the molding means are discharged and the side and end folds of the inclosure are completed. 75

5. In a cigarette packaging machine, devices for separately feeding an inclosure and a predetermined number of cigarettes in bunched form to a predetermined point in position for simultaneous discharge, means 80 for compressing the cigarettes before association with the inclosure, a movable molding means into which the inclosure and bunch of cigarettes are simultaneously inserted, and compressing, shaping and folding mechanism to which the inclosure and cigarettes are delivered from the molding means. 85

6. In a cigarette packaging machine, devices for feeding an inclosure and a specific number of cigarettes in compressed bunched form to a predetermined point and disposing the cigarettes over the inclosure, a movable molding means having a step by step rotation into which the inclosure and cigarettes are simultaneously inserted, mechanism for compressing and shaping the package and to which the latter is delivered from the mold wheel, the side and end folds of the inclosure being completed by the latter mechanism. 100

7. In a cigarette packaging machine, devices for feeding an inclosure and a compressed bunch of a specific number of cigarettes to a predetermined point of assemblage, a movable molding means in which the inclosure and cigarettes are simultaneously disposed, and mechanism for completing the compression and shaping of the cigarettes and folding of the inclosure and to which the inclosure and cigarettes from the molding means are discharged. 105 110

8. In a cigarette packaging machine, the combination of devices for feeding an inclosure blank and a compressed bunch of cigarettes having a specific number to a predetermined point and disposing the cigarettes over the inclosure blank, a movable molding means into which the bunch of cigarettes and the inclosure blank are simultaneously inserted, the inclosure being partially folded over the bunch of cigarettes by the movement of the molding means, and mechanism for compressing and shaping and completing the folds of the inclosure 120 125 and into which the inclosure and bunch of cigarettes from the molding means are discharged.

9. In a cigarette packaging machine, mechanism for feeding an inclosure blank 130

- to a predetermined point, the blank being cut to desired dimensions before reaching said point, mechanism for compressing and disposing a bunch of cigarettes of a specific 5 number to one side of the central portion of and over the inclosure blank by a continuous progressive movement of the bunch of cigarettes, and mechanism for molding, shaping and compressing the bunch and 10 folding the inclosure blank.
10. In a cigarette packaging machine, devices for feeding an inclosure blank preliminarily cut to size and compressing and disposing a bunch of cigarettes over the 15 blank near one edge of the latter by a continuous operation, and mechanism for completing the shape of the package and the folds of the inclosure blank relatively to the bunch of cigarettes.
11. In a cigarette packaging machine, devices for feeding a cut inclosure blank and compressing and disposing a bunch of cigarettes in receptive adjacency above and out 20 of contact with relation to the said blank, the bunch of cigarettes and inclosure blank being disposed nearer one side edge than the other side edge of said blank, and means for completing the shape of the bunch and the inclosure blank and for folding the latter 25 around the bunch.
12. In a cigarette packaging machine, devices for compressing and disposing a bunch of cigarettes and cutting and feeding an inclosure blank and a liner in associated relation 30 in receptive adjacency below said bunch of cigarettes, the cigarettes being disposed nearer one edge of the blank and liner than the other, and means for simultaneously receiving and completing the shape of the 35 bunch of cigarettes and the inclosure and liner and folding the latter with relation to the bunch of cigarettes.
13. In a cigarette packaging machine, devices for compressing and disposing a bunch 40 of cigarettes and feeding an inclosure blank in receptive adjacency to said bunch of cigarettes, and mechanism having a pocket with curved corners and in part yielding in 45 operation for completing the shape of the bunch and the inclosure blank and for folding the latter around the bunch and giving the package a rounded corner contour.
14. In a cigarette packaging machine, devices for selecting a definite number of cigarettes, compressing them into bunch form and disposing the bunch in a discharging 50 position, by a continuous operation, feeding and pasting a cut inclosure blank and positioning the latter in receptive adjacency 55 below the bunch of cigarettes, and means for simultaneously receiving and completing the shape of the bunch of cigarettes and the inclosure and folding the inclosure with 60 relation to the bunch of cigarettes.
15. In a cigarette packaging machine, de- 65 vices for feeding a cut inclosure blank to a predetermined point and during the movement thereof applying adhesive material to different portions of the same, disposing a bunch of cigarettes adjacent to the inclosure 70 blank, means for simultaneously receiving and completing the shape of the bunch of cigarettes and the inclosure blank and folding the latter with relation to the bunch of cigarettes, and separate means for compressing 75 the packages of cigarettes to a uniform bulk.
16. In a cigarette packaging machine, devices for first cutting and then progressively feeding an inclosure blank and for placing a coupon thereon during the feeding movement of the same, mechanism for disposing a bunch of cigarettes adjacent to the blank, means for completing the shape of the bunch and the inclosure blank and 80 for folding the latter around the bunch, and separate means for compressing the packages to a uniform bulk.
17. In a cigarette packaging machine, devices for cutting and feeding an inclosure 85 blank to a predetermined point and applying adhesive material to different portions thereof during its feeding movement, mechanism for disposing a bunch of cigarettes in position between the pasted portions of the blank, means for completing the shape of the bunch and inclosure blank and for folding the latter around the bunch, and separate means for compressing the packages of cigarettes to a uniform bulk.
18. In a cigarette packaging machine, means for feeding a cut inclosure blank to a predetermined point, the feeding means embodying hook arms with forwardly projecting heads having vertically straight edges which engage one edge of the cut blank, devices for disposing a bunch of cigarettes in receptive adjacency over the inclosure blank, and mechanism for completing the shape of the bunch and the inclosure blank and for folding the latter around the bunch.
19. In a cigarette packaging machine, devices for feeding a cut inclosure blank to a predetermined point, the feeding devices embodying endless chain belts having arms with upper angular extremities projecting forwardly therefrom and having front vertically straight blank engaging edges, and devices for disposing a bunch of cigarettes 110 in receptive adjacency to and over the inclosure blank and completing the bunch and folding the blank therearound.
20. In a cigarette packaging machine, mechanism for feeding a cut inclosure blank 115 consisting of a table having endless chain belts movable therethrough and provided with arms having angular extremities to engage an edge portion of the blank as it is moved by said arms, means for pasting por- 120
- 130

tions of the blank, grooved rollers for engaging the blank in its feeding progress after it is pasted to clear the pasted portions thereof, and mechanism for disposing 5 a charge of cigarettes in the blank and shaping the cigarettes and blank and folding the latter around the cigarettes.

21. In a cigarette packaging machine, devices for feeding a cut inclosure blank consisting of endless chain belts having projecting devices to engage an edge portion of the blank, registering rollers to take the blank after it reaches the inner terminal positions of the endless chain belts, and mechanism for disposing a charge of cigarettes in the blank and shaping the latter and the cigarettes and folding the blank around the cigarettes, the registering rollers disposing the cut blank under and at a distance from 20 the charge of cigarettes.

22. In a cigarette packaging machine, mechanism including upwardly projecting progressive devices having engaging edges which are in part in advance of each other 25 for feeding a blank member and disposing another member thereon during the progress of the first member and disposing the one edge of the one member coincident with the corresponding edge of the remaining 30 member, and mechanism for providing and depositing a charge of cigarettes in the associated blank members and for shaping the charge of cigarettes and folding the blank members around the said charge.

23. In a cigarette packaging machine, a feed table, having means movable longitudinally thereof including upwardly projecting progressive devices having engaging edges which are in part in advance of each 40 other for feeding an inclosure blank thereover, mechanism for associating another inclosure blank with the first named blank while the latter is in motion and disposing the one edge of the one member coincident 45 with the corresponding edge of the remaining member, and mechanism for disposing a charge of cigarettes in the associated blanks and shaping the charge and folding the blanks about the charge.

24. In a cigarette packaging machine, a table having means for longitudinally moving an inclosure blank thereover, a bridge supported by and located over the table under which the said blank has movement, 55 mechanism including upwardly projecting progressive devices having engaging edges which are in part in advance of each other for disposing a second blank member on the bridge and associating it with the first

60 blank member, the one edge of the one blank being disposed coincident with the corresponding edge of the other blank, one blank being also wider and shorter than the other blank, and mechanism for placing a 65 charge of cigarettes in the associated blank

members and shaping said charge and folding the blank members therearound.

25. In a cigarette packaging machine, a table having mechanism including upwardly projecting progressive devices having engaging edges which are in part in advance of each other for moving an inclosure blank longitudinally thereover, mechanism for cutting and feeding an inclosure blank and depositing it on the said 70 table, the inclosure blank being moved to a predetermined point, means engaging edges in advance of other edges thereof for depositing a liner blank on the inclosure blank and coinciding the one edge of one blank 75 with the corresponding end edge of the other blank, and mechanism for positioning a charge of cigarettes in receptive adjacency to the combined blank and forcing them into the latter and then shaping the charge 80 and blank and folding said blank around the charge.

26. In a cigarette packaging machine, an inclosure feeding mechanism including upwardly projecting progressive devices having engaging edges which are in part in advance of each other having means for moving an inclosure blank thereover, mechanism for cutting and feeding another blank inclosure onto the first named inclosure blank, the blank inclosures being associated so that the one edge of one will coincide with the one edge of the other and the remaining edge portions of one will project relatively to the corresponding edge 90 portions of the other, and mechanism for depositing a charge of cigarettes in the united blank inclosures and for completing the inclosure.

27. In a cigarette packaging machine, 105 feeding mechanism having means for moving an inclosure thereover embodying upstanding arms with forwardly projecting upper hooked extremities with vertically straight front edges and forming overhanging shoulders, a bridge over said means under which said inclosure is fed, mechanism for cutting and feeding another inclosure member to the bridge and from the latter on the first inclosure, the one inclosure being 110 fed by the vertically straight edge of the hooked heads and the other inclosure by the forward edges of the arms, the inclosure member being associated with the first named inclosure in such manner as to have 115 edge projection relatively thereto, and means for depositing a charge of cigarettes in the associated inclosures and completing the package.

28. In a cigarette packaging machine, 125 mechanism for feeding inclosure members, one on the other, in such relation that edge portions of the two members will be projected beyond adjacent edge portions of one another, said mechanism including up- 130

- standing arms having inclosure engaging edges in advance of other inclosure engaging edges thereof, and means for depositing a charge of cigarettes in the associated members and completing the package. 65
29. In a cigarette packaging machine, mechanism for feeding one inclosure member on another inclosure member and disposing them out of edge alinement so that 10 the inner inclosure member will project at one extremity beyond the outer inclosure member and the outer inclosure member project at one extremity beyond the inner inclosure member, said mechanism including upstanding arms having inclosure engaging edges in advance of other inclosure members and completing the package. 15
30. In a cigarette packaging machine, mechanism including upwardly projecting progressive devices having inclosure engaging edges in advance of other inclosure 20 edges thereof for feeding a single inclosure member and placing a second inclosure member of different dimensions on the first inclosure member so that the one extremity and side edge portion of the 25 one member will project beyond the adjacent extremity and side edge portion of the other member, and mechanism for depositing a charge of cigarettes in the associated members and completing the package. 30
31. In a cigarette packaging machine, mechanism including upwardly extending arms having advanced bearing edges for associating and unitedly feeding inclosure members, the members having an overlying 35 position relatively to each other with one set of edges coinciding and the remaining edges out of coincidence, and mechanism for depositing a charge of cigarettes in associated relation to the members and completing the package. 40
32. In a cigarette packaging machine, mechanism for feeding an inclosure blank consisting of a table having endless conveying means with arms provided with projecting extremities, the inclosure blank being engaged by front edges of a portion of 45 said arms below the projecting extremities of the latter, an elevated means on a portion of the table through which the said 50 arms and their projecting extremities have movement, the projecting extremities of the arms extending above the elevated means, mechanism for feeding other inclosure blanks to said elevated means for engagement by the projecting extremities of the 55 arms, the blanks on the elevated means being moved onto and associated with the blanks moving on the said table, and mechanism for depositing cigarettes in the 60
- associated blanks and for shaping and inclosing the said cigarettes with the associated blanks. 65
33. In a cigarette packaging machine, a table having feeding mechanism provided with projecting means with vertically straight advanced bearing edges for simultaneously moving and associating two inclosure blanks so that one blank will be applied on the other, and mechanism for depositing cigarette charges in the associated blanks and for completing the package. 70
34. In a cigarette packaging machine, a table having feeding mechanism movable thereover and embodying projecting means with vertically straight advanced bearing edges for simultaneously engaging and relatively feeding two inclosure blanks so that the edge of one will be slightly in advance of the edge of the other and for causing the one blank to be placed on the other, and mechanism for supplying charges of cigarettes to the blanks and for completing the package. 75
35. In a cigarette packaging machine, a table having feeding mechanism moving thereover provided with projecting means with vertically straight advanced bearing edges for simultaneous engagement with normally separated inclosure blanks, a part of the blanks being above the remaining 80 blanks, said projecting means effecting an association of the two blanks, and means for charging the blanks with cigarettes and completing the package. 85
36. In a cigarette packaging machine, a table having feeding means movable thereover provided with projections, a bridge over a part of the table through which said projections also have movement, the projections being arranged to receive a blank 90 inclosure and regularly move the same over the table under the bridge, mechanism for supplying and cutting other inclosure blanks which are deposited on the bridge and engaged by the projecting means and 95 moved simultaneously with the inclosure blanks below and placed on the blanks moving under the bridge, and mechanism for charging the associated blanks with cigarettes and completing the charged packages. 100
37. In a cigarette packaging machine, a table having conveyer means movable thereover provided with arms having projecting heads, a bridge mounted over a portion of the table through which the arms and heads 105 have movement, the arms being arranged to receive inclosure blanks and feed the latter under the bridge, the bridge having flange means at one side to decrease the width of the same relatively to the table below, mechanism for supplying other inclosure blanks on the bridge in advance of the heads of the arms and moved by the said heads over the 110
- 115
- 120
- 125

bridge onto the blanks below so that the blanks will have projecting side and end edge portions relatively to each other, and mechanism for charging the associated 65 blanks with cigarettes and folding the blanks and completing the package.

38. In a cigarette packaging machine, a table having means for feeding blanks longitudinally thereover to a predetermined 10 point, pasting mechanism having devices for applying lines of paste to the blanks and also alternately operating devices for spotting the blanks with paste at different portions thereof in addition to the paste lines, 15 rollers on the table for engaging the blanks, the rollers being provided with grooves to clear the pasted portions of the blanks, and mechanism for depositing charges of cigarettes in the blanks and folding the latter 20 and completing the packages.

39. In a cigarette packaging machine, mechanism for feeding an inclosure blank to a predetermined point, mechanism for supplying and cutting material into blank sizes 25 and feeding the blanks so prepared over and onto the first named blanks, means for feeding a coupon onto the associated blanks, and mechanism for depositing the charge of cigarettes on the associated blanks and folding 30 said blanks around the cigarettes and completing the package.

40. In a cigarette packaging machine, a mechanism for feeding an inclosure blank consisting of a table having conveying 35 means to engage the blank, mechanism for applying adhesive material to the blank while in motion and embodying devices for spotting the blank with adhesive material at different portions thereof and also for applying adhesive material to other portions of the blank, mechanism for preparing and supplying an additional inclosure blank over 40 and upon the blank having the adhesive material thereon, and mechanism for charging the associated blanks with cigarettes and folding the blanks over the cigarettes and completing the package.

41. In a cigarette packaging machine, a table having feeding mechanism movable 50 longitudinally thereof to successively receive blanks fed to the table, devices for applying adhesive material to different portions of the blanks as they are fed over the table, means for depositing a coupon on the blanks, and means for charging the blanks with cigarettes and folding the blanks around the latter and completing the package.

42. In a cigarette packaging machine, a 60 table having mechanism for feeding an inclosure blank longitudinally thereover, registering rollers on the table beyond the inner limit of the said feeding mechanism, delivery rollers at a distance inwardly from the

registering rollers, and mechanism for 65 charging the blank with cigarettes and shaping the package and completing the folds of the blank.

43. In a cigarette packaging machine, a table having means for moving an inclosure 70 blank longitudinally thereover, mechanism for cutting blanks of predetermined dimensions and causing them to be disposed on the said table, mechanism for charging the blanks with cigarettes and shaping and completing 75 the inclosure of the cigarettes, and separate means for compressing the packages of cigarettes to a uniform bulk.

44. In a cigarette packaging machine, a table having longitudinal slots therein, endless conveying means movable over the table and provided with projecting hook arms extending through the slots to engage inclosure blanks, mechanism to engage inclosure blanks and feed them to a predetermined 80 point, mechanism for placing a charge of cigarettes on the blank and discharging the same with the blank from the table, and mechanism for shaping the blank and its charge of cigarettes and completing 85 the folds of the blank.

45. In a cigarette packaging machine, mechanism for assembling a predetermined number of cigarettes and inspecting conveying 90 means disposed to receive the successive charges of the cigarettes from said mechanism, means for relieving the conveying means of the charges of cigarettes, mechanism for arranging the charges of cigarettes in a more compact mass and disposing 95 them in position for discharge, mechanism for feeding an inclosure in receptive adjacency to the cigarettes, and mechanism for discharging the cigarettes and shaping and folding the inclosure.

46. In a cigarette packaging machine, mechanism for assembling a predetermined number of cigarettes, inspecting conveying 100 means disposed to receive the charges of cigarettes from said mechanism, means for relieving the conveying means of the charges of cigarettes, mechanism for giving the successive charges of cigarettes a preliminary compression to dispose them in close association and place them in a position for discharge, mechanism for feeding an inclosing 105 wrapper in receptive adjacency to each charge of cigarettes, and means for discharging the cigarettes and completing the inclosure thereof.

47. In a cigarette packaging machine, mechanisms for assembling cigarettes and expelling them in charges of predetermined numbers, open inspecting conveying means to receive the successive charges of cigarettes from the said mechanism, means for relieving the conveying means of the charges of cigarettes, mechanism for dis-

posing the charges of cigarettes in discharging position for inclosure, mechanism for feeding wrappers in receptive adjacency to the charges of cigarettes, and mechanism for completing the inclosure of the charges of cigarettes by the wrappers.

48. In a cigarette packaging machine, mechanism for feeding an inclosure blank to a predetermined point, mechanism for 10 assembling specific charges of cigarettes and conveying them in open inspecting condition to a point of discharge, and mechanism for closely associating the constituents of the charges of cigarettes and discharging the 15 latter into the inclosure blanks and wrapping said blanks about the charges.

49. In a cigarette packaging machine, mechanism for assembling cigarettes and expelling them in charges of predetermined 20 numbers, open inspecting conveying means which receive and carry the successive 25 charges away from the assembling mechanism, mechanism for closely associating the individual components of the charges of cigarettes and disposing the charges in discharging position for inclosure, mechanism for feeding wrappers in receptive adjacency to the charges of cigarettes, and mechanism for completing the inclosure of the charges 30 of cigarettes by the wrappers.

50. In a cigarette packaging machine, mechanism for exposing and conveying charges of cigarettes of predetermined numbers to a point of discharge therefrom, 35 mechanism for closely associating and disposing the charges of cigarettes in discharging position for inclosure, mechanism for feeding wrappers in receptive adjacency to the charges of cigarettes, and mechanism for 40 completing the inclosure of the charges of cigarettes by the wrappers.

51. In a cigarette packaging machine, mechanism for assembling cigarettes, open inspecting conveying means to receive successive charges of cigarettes from the assembling mechanism, means for simultaneously expelling charges of cigarettes of predetermined numbers from the assembling mechanism into the conveying means and also 50 from the latter, mechanism for disposing the charges of cigarettes relieved from the conveying means in discharging position for inclosure, mechanism for feeding wrappers in receptive adjacency to the charges of cigarettes, and mechanism for completing the inclosure of the charges of cigarettes by the wrappers.

52. A cigarette packaging machine having mechanism for assembling cigarettes in 60 charges of predetermined numbers and conveying the successive charges in open inspecting condition adjacent to a discharging point, mechanism for feeding wrappers to a position to receive the charges of cigarettes, and mechanism for discharging the 65

successive charges of cigarettes into the wrappers and completing the inclosure of the charges of cigarettes by the wrappers.

53. A cigarette packaging machine having mechanism for assembling cigarettes in 70 charges of predetermined numbers and conveying distinct charges in open condition for inspection and delivering the charges of cigarettes to a discharging point, mechanism for feeding wrappers in receptive adjacency to the charges of cigarettes, and mechanism for discharging the cigarettes into the wrappers and completing the inclosure of the charges of cigarettes by the wrappers.

54. In a cigarette packaging machine, 80 mechanism for assembling cigarettes and expelling them in charges of predetermined numbers, a compression chamber into which the charges of cigarettes are delivered, the compression chamber being provided with 85 means for closely associating the constituents of the charges of cigarettes and placing the charges in position for discharge, mechanism for feeding wrappers in receptive adjacency to the charges of cigarettes, and mechanism for discharging the charges of cigarettes and completing the inclosure of the charges of cigarettes by the wrappers.

55. In a cigarette packaging machine, mechanism for assembling cigarettes and expelling them in charges of predetermined numbers, a compression chamber having means for closely associating the components of the individual charges of cigarettes and disposing the charges successively in 100 discharging position, open conveying means between the assembling mechanism and the compression chamber to receive the successive charges of cigarettes, mechanism for feeding wrappers in receptive adjacency to 105 the charges of cigarettes, and mechanism for discharging the charges of cigarettes into and with the wrappers and completing the inclosure of the charges of cigarettes by the wrappers.

56. In a cigarette packaging machine, mechanism for assembling cigarettes and expelling them in charges of predetermined numbers, mechanism for imparting a preliminary pressure to the individual charges 115 of cigarettes and disposing said charges in discharging position, open means for conveying the individual charges of cigarettes from the assembling mechanism to the said preliminary pressure mechanism, and mechanism for discharging the cigarette charges into the wrappers in succession and completing the inclosure of the charges of cigarettes by the wrappers.

57. In a cigarette packaging machine, 125 mechanism for assembling cigarettes and expelling them in charges of predetermined numbers, mechanism for successively feeding wrappers cut to proper size in receptive adjacency to and out of contact with rela- 130

tion to the charges of cigarettes, mechanism for discharging the cigarette charges successively into the wrappers, mechanism for shaping and pressing the charges of cigarettes and wrappers and completing the inclosure of the charges of cigarettes by the wrappers, and separate means for compressing the packages of cigarettes to a uniform bulk.

10 58. In a cigarette packaging machine, mechanism for grouping cigarettes in charges of predetermined numbers, open inspecting conveying means to receive the individual groups of cigarettes and deliver the latter adjacent to a point of discharge, mechanism for feeding wrappers in receptive adjacency to the groups of cigarettes, and mechanism for discharging the groups of cigarettes into the wrappers and completing the in-
20 closure of the groups by the wrappers.

59. In a cigarette packaging machine, mechanism for assembling cigarettes in charges of predetermined numbers, open inspecting conveying means for receiving the separated charges of cigarettes in succession and conveying said charges by a step by step movement adjacent to a point of discharge, mechanism for simultaneously expelling the charges of cigarettes from the assembling
25 mechanism into the conveying means and from the latter, mechanism for feeding wrapper blanks in receptive adjacency to the charges of cigarettes, and mechanism for successively discharging the charges of cigarettes into the wrapper blanks and folding the said blanks around the charges of cigarettes.

60. In a cigarette packaging machine, mechanism for assembling cigarettes in groups of a predetermined number and expelling said groups, the groups having one or more spaces provided therein when they are expelled, mechanism for preliminarily compressing and closely associating the cigarettes and placing them in a discharging position, mechanism for disposing a wrapper in receptive adjacency to each charge of cigarettes and discharging the cigarettes thereinto, and mechanism for completing the inclosure of the cigarettes by folding the wrapper therearound.

61. In a cigarette packaging machine, mechanism for assembling cigarettes and expelling them in charges of predetermined numbers with one or more spaces between the constituents of the charges, mechanism for closely associating and positioning the components of the several charges and placing the latter in discharging position, mechanism for feeding blank wrappers in receptive adjacency to the charges of cigarettes, and mechanism for discharging the cigarettes into the blank wrappers and completing the inclosure of the charges of cigarettes by the wrappers.

62. In a cigarette packaging machine, mechanism for assembling cigarettes in charges of predetermined numbers wherein the components are partially spaced by omitting one or more cigarettes from each charge in the discharge of the latter, mechanism for arranging the charges of cigarettes in compact mass and placing them in discharging position, and mechanism for inclosing the successive charges. 75

63. In a cigarette packaging machine, mechanism for assembling cigarettes in charges of predetermined numbers wherein the components are partially spaced by omitting one or more cigarettes from each charge in the discharge of the latter, mechanism for arranging the charges of cigarettes in compact mass and placing them in discharging position, and mechanism for inclosing and shaping the successive charges. 80

64. In a cigarette packaging machine, mechanism for assembling cigarettes and expelling them in charges wherein the components are partially spaced by omitting one or more cigarettes from each charge in the discharge of the latter, and mechanism for closely arranging the component cigarettes of the charges and for successively inclosing the charges. 85

65. In a cigarette packaging machine, mechanism for assembling and expelling cigarettes in charges of predetermined numbers wherein the components are partially spaced and loose by omitting one or more cigarettes from each charge in the discharge of the latter, mechanism for receiving the successive charges and rearranging and closely associating the component cigarettes of the charges, and mechanism for inclosing the successive charges. 95

66. In a cigarette packaging machine, mechanism for assembling cigarettes and expelling them in charges of predetermined numbers wherein the components are partially spaced and in loose condition, open inspecting conveying means for receiving the successive charges from the assembling mechanism and transmitting them to a predetermined point, mechanism for closely associating and arranging the component cigarettes of the charges and placing the latter in position for discharge, and mechanism for applying inclosures about the charges of cigarettes. 100

67. In a cigarette packaging machine, mechanism for assembling a plurality of cigarettes in position for expulsion from the said mechanism, means for expelling predetermined numbers of the cigarettes from said mechanism so that the cigarettes will be in partial spaced relation by omitting one or more cigarettes from each charge in the discharge of the latter, mechanism for closely associating and arranging the component cigarettes of the several charges, and 110

mechanism for inclosing the charges of cigarettes.

68. In a cigarette packaging machine, mechanism for assembling cigarettes in expelling position and in part shielding the assembled cigarettes, means for simultaneously expelling charges of cigarettes from the assembling mechanism and spacing the component cigarettes in part by omitting 10 one or more cigarettes from each charge in the discharge of the latter, and mechanism for closely associating the successive charges of cigarettes so expelled and inclosing them.

69. In a cigarette packaging machine, 15 mechanism for assembling cigarettes in rows provided with shielding means for a portion of the cigarettes, means for expelling the cigarettes from the assembling mechanism having an organization corresponding 20 to the shielded portion of the cigarettes to effect an expulsion of charges of cigarettes of predetermined numbers with a space between portions of the cigarettes of each charge by omitting one or more cigarettes 25 from each charge in the discharge of the latter, mechanism for closely associating the charges of cigarettes and taking up the space between a portion of the cigarettes, mechanism for feeding wrapper means adjacent to and discharging the charges of 30 cigarettes into said wrapper means, and mechanism for completing the inclosure of the cigarettes.

70. In a cigarette packaging machine, 35 mechanism for assembling cigarettes having means for shielding a part of the cigarettes, means organized relatively to the shielding means of the assembling mechanism to effect an expulsion of a predetermined number of cigarettes in distinct 40 charges from said mechanism and produce a space in relation to the cigarettes of each charge by omitting one or more cigarettes from each charge in the discharge of the latter, mechanism for closely associating 45 and compressing the charges of cigarettes, and mechanism for inclosing the cigarettes.

71. In a cigarette packaging machine, 50 mechanism for assembling a plurality of cigarettes in separated vertical rows and shielding a portion of the ends of the cigarettes, expelling means organized to push a predetermined number of cigarettes out of the assembling mechanism and having a 55 clearance relatively to the shielding means, mechanism for closely associating and preliminarily pressing the successive charges of cigarettes from the assembling mechanism, and mechanism for inclosing the successive 60 charges of cigarettes.

72. In a cigarette packaging machine, a molding means having a plurality of pockets, each pocket provided with a movable bottom with an inward projection, mechanism for successively disposing charges of

cigarettes and inclosures therefor in the pockets of the molding means, mechanism for discharging the cigarettes and inclosing means successively from the pockets of the molding means, a shaping and compression means into which the charges of cigarettes and their inclosures are discharged, the shaping and compression means having folding devices coöperating therewith to complete the inclosure of the packages and 75 also operable to give the packages a uniform size, and mechanism for expelling the completed packages from the shaping and compression means.

73. In a cigarette packaging machine, a 80 mold wheel having a plurality of pockets with movable bottoms, the movable bottoms having inwardly extending stems with projections thereon, mechanism for disposing charges of cigarettes and wrappers in the 85 mold wheel pockets against the said movable bottom, mechanism for moving the bottoms in outward position to receive the charges of cigarettes and wrappers, separate mechanism for discharging the charges of 90 cigarettes and wrappers from the mold wheel pockets, and compressing and folding mechanism to which the charges of cigarettes and the wrappers are successively discharged from the mold wheel pockets. 95

74. In a cigarette packaging machine, a mold wheel having a plurality of pockets with movable bottoms therein, the bottoms being provided with concave side edge portions, mechanism for disposing charges of 100 cigarettes and wrappers in the pockets of the mold wheel against the movable bottoms and shaping a portion of the corners of the wrappers and charges of cigarettes in a rounded contour, compressing and folding 105 mechanism, the latter mechanism also having means for giving the remaining corners of the packages of cigarettes a rounded contour, and mechanism for discharging the charges of cigarettes and wrappers from the mold wheel pockets into operative relation to the compressing and folding mechanism and for discharging the packages from said compressing and folding mechanism. 110

75. In a cigarette packaging machine, a mold wheel having a plurality of pockets, mechanism for disposing charges of cigarettes and wrappers in the pockets, compression and folding mechanism having devices for compressing to a uniform bulk, mechanism for discharging the charges of cigarettes and wrappers into operative relation to the compression and folding mechanism, and mechanism for discharging the 125 closed packages from the compression mechanism.

76. In a cigarette packaging machine, a mold wheel having a plurality of pockets, mechanism for disposing charges of ciga- 130

rettes and wrappers in the pockets of the mold wheel, and mechanism for receiving the charges of cigarettes and wrappers from the mold wheel and compressing said charges with a uniform pressure and folding the wrappers about the cigarette charges.

77. In a cigarette packaging machine, a mold wheel having a plurality of pockets, mechanism for disposing charges of cigarettes and wrappers in the pockets of the mold wheel, mechanism for receiving the charges of cigarettes and wrappers from the mold wheel and compressing and shaping said charges and wrappers, mechanism co-
operating with said receiving mechanism for controlling the pressure on each cigarette charge and wrapper to render said pressure uniform and give the packages similar dimensions, mechanism for completing the folds of the wrapper, and mechanism for discharging the packages from the said receiving mechanism.

78. In a cigarette packaging machine, a mold wheel having a plurality of pockets, mechanism for disposing charges of cigarettes and wrappers in the pockets of the mold wheel, compression and shaping mechanism for receiving the charges of cigarettes and the wrappers from the mold wheel, said compression and shaping mechanism embodying a sectional plunger wherein one part is movable with relation to another part and in advance of the latter part when in receiving position for the cigarette charges and wrappers, mechanism for completing the folds of the wrappers, and mechanism for discharging the packages from the compression and shaping mechanism.

79. In a cigarette packaging machine, a mold wheel having a plurality of pockets, mechanism for disposing charges of cigarettes and wrappers in the pockets of the mold wheel, compression and shaping mechanism for receiving the charges of cigarettes and the wrappers from the mold wheel, said compression and shaping mechanism embodying a plunger provided with means for giving the same a resilient compensating operation and also provided with means which yields when engaged by the packages to prevent too resistful primary pressure on the packages when the latter are received by the said compression and shaping mechanism, mechanism for completing the folds of the wrappers, and mechanism for discharging the packages from the compression and shaping mechanism.

80. In a cigarette packaging machine, mechanism for supplying and positioning charges of cigarettes and wrappers, and compression and shaping mechanism for receiving the charges of cigarettes and wrappers and provided with sliding means having a spring controlled recession action for engaging the charges of cigarettes and

wrappers with a resilient compensating pressure to prevent too resistful primary pressure on the packages when the latter are received by the said compression and shaping mechanism, and mechanism for completing the inclosure of the charges and discharging the latter from the compression and shaping mechanism.

81. In a cigarette packaging machine, mechanism for supplying and positioning charges of cigarettes and wrappers for progressive treatment, mechanism for compressing and shaping the charges of cigarettes and wrappers and partially completing the folds of the wrappers, oppositely moving vertically reciprocating devices for forming the primary end folds of the wrappers while the charges of cigarettes and wrappers are in the compressing and shaping mechanism, a movable device for forming the first side folds at the ends of the packages, fixed means for completing the side folds at the ends of the packages, said folding instrumentalities operating when the packages have been compressed and shaped, and mechanism for discharging the packages from the compressing and shaping mechanism.

82. In a cigarette packaging machine, mechanism for supplying and positioning charges of cigarettes and wrappers associated therewith for progressive treatment, mechanism for compressing and shaping the charges of cigarettes and wrappers and completing the folds of the wrappers about the charges, a reciprocating shuttle for receiving and further treating the packages of cigarettes, the packages of cigarettes being successively discharged from the shuttle by subsequent introduction of packages therein, and mechanism for moving the packages away from the shuttle and conveying them from the machine.

83. In a cigarette packaging machine, mechanism for supplying and positioning charges of cigarettes and wrappers associated therewith for progressive treatment mechanism for receiving the charges of cigarettes and wrappers and completing the folds of the latter, a reciprocating shuttle into which the packages of cigarettes are delivered for further treatment, the packages of cigarettes being expelled from the shuttle by the successive introduction of packages in the shuttle, and mechanism for discharging the packages and conveying them away from the machine.

84. In a cigarette packaging machine, mechanism for supplying, compressing and placing charges of cigarettes in inclosure means and completing the said inclosure means relatively to the charges of cigarettes, and a reciprocating shuttle into which the packages of cigarettes are delivered for further treatment, the packages being expelled from the shuttle by the successive introduc-

tion of packages in the shuttle, and mechanism for discharging the packages and conveying them away from the machine.

85. In a cigarette packaging machine, mechanism for supplying and placing charges of cigarettes in inclosure means and completing said inclosure means relatively to the charges of cigarettes, a reciprocating shuttle into which the packages of cigarettes are delivered for further treatment, the packages being individually expelled from the shuttle by the successive introduction of packages into the shuttle, mechanism for holding the end folds of the inclosure means while the packages are in the shuttle, and mechanism for discharging the packages from the machine.

86. In a cigarette packaging machine, mechanism for supplying and placing charges of cigarettes in inclosure means and completing the inclosure means relatively to the charges of cigarettes, a reciprocating shuttle into which the packages of cigarettes are delivered for further treatment, the packages being expelled from the shuttle by the successive introduction of packages in the shuttle, mechanism for moving the packages away from the outlet portion of the shuttle, and mechanism for discharging the packages from the machine.

87. In a cigarette packaging machine, mechanism for supplying and placing charges of cigarettes in inclosure means and completing said inclosure means relatively to the charges of cigarettes, a reciprocating shuttle having a yielding component and into which the packages of cigarettes are successively delivered for further treatment, the packages being expelled from the shuttle by the successive introduction of packages in the shuttle, and mechanism for discharging the packages from the rear outlet extremity of the shuttle.

88. In a cigarette packaging machine, mechanism for supplying and placing charges of cigarettes in inclosure means and completing said inclosure means relatively to the charges of cigarettes, a reciprocating shuttle having a lower non-yielding component and an upper yielding component, the packages of cigarettes being successively delivered into the shuttle for further treatment and expelled from the shuttle by the successive introduction thereof into the shuttle, and mechanism for discharging the packages from the rear outlet portion of the shuttle.

89. In a cigarette packaging machine, mechanism for supplying and placing charges of cigarettes in inclosure means and completing said inclosure means relatively to the charges of cigarettes, a reciprocating shuttle into which the packages of cigarettes are successively delivered for further treatment, the packages being ex-

pelled from the shuttle by the successive introduction of other packages thereinto, and mechanism for moving the packages away from the rear portion of the shuttle and discharging them from the machine.

90. In a cigarette packaging machine, mechanism for supplying and placing charges of cigarettes in inclosure means and completing said inclosure means relatively to the charges of cigarettes, a reciprocating shuttle into which the packages of cigarettes are successively delivered for further treatment, the packages being expelled from the shuttle by the successive introduction of other packages thereinto, and plungers operating in planes at right angles to each other in rear of the shuttle to move the packages away from the rear of the shuttle and to discharge the packages from the machine.

91. In a cigarette packaging machine, mechanism for supplying and placing charges of cigarettes in inclosure means and completing said inclosure means relatively to the charges of cigarettes, reciprocating means into which the packages of cigarettes are successively delivered for further treatment and from which they are expelled by the continuous supply of packages thereto, banding mechanism for supplying bands from the rear portion of said reciprocating means, and mechanism for discharging the banded packages from the machine.

92. In a cigarette packaging machine, mechanism for supplying and placing charges of cigarettes in inclosure means and completing said inclosure means relatively to the charges of cigarettes, a reciprocating shuttle into which the packages of cigarettes are successively delivered for further treatment, the packages being expelled from the shuttle by the successive introduction of other packages thereinto, mechanism for feeding and holding bands across the rear portion of the shuttle, the bands being applied to the packages by the movement of the latter thereagainst, and mechanism for discharging the banded packages from the machine.

93. In a cigarette packaging machine, mechanism for supplying and placing charges of cigarettes in inclosure means and completing said inclosure means relatively to the charges of cigarettes, a reciprocating shuttle into which the packages of cigarettes are successively delivered for further treatment, the packages being expelled from the shuttle in endwise positions by the successive introduction of other packages into the shuttle, mechanism for feeding and cutting predetermined lengths of bands and disposing the said bands across the rear portion of the shuttle, the bands being applied to the ends of the packages by the movement of the packages thereagainst, and mechanism

for discharging the banded packages from the machine.

94. In a cigarette packaging machine, mechanism for supplying and placing charges of cigarettes in inclosure means and completing said inclosure means relatively to the charges of cigarettes, mechanism for compressing and shaping the charges of cigarettes and inclosure means, a reciprocating shuttle into which the packages of cigarettes are successively delivered for further treatment, the packages being expelled from the shuttle in endwise positions by the successive introduction of other packages into the shuttle, mechanism for feeding and cutting predetermined lengths of bands and disposing said bands across the rear portion of the shuttle, the bands being applied to the ends of the packages by the movement of the latter against the bands, and mechanism for moving the banded packages away from the rear portion of the shuttle and simultaneously actuating the band feeding and cutting mechanism.

95. In a cigarette packaging machine, mechanism for supplying and placing charges of cigarettes in inclosure means and completing said inclosure means relatively to the charges of cigarettes, a reciprocating shuttle into which the packages of cigarettes are successively delivered for further treatment and regularly discharged from the shuttle, banding mechanism for feeding and cutting predetermined lengths of bands and disposing the said bands across the rear portion of the shuttle, the bands being applied to the ends of the packages by the movement of said packages against the bands, mechanism for moving the banded packages away from the rear portion of the shuttle, and mechanism for rendering the band feeding and cutting mechanism operative and inoperative relatively to the shuttle.

96. In a cigarette packaging machine, mechanism for supplying and inclosing charges of cigarettes, a reciprocating shuttle into which the packages of cigarettes are successively delivered for treatment and discharged from the shuttle by the successive introduction of the packages into the latter, banding mechanism for feeding and cutting predetermined lengths of bands and disposing said bands across the rear portion of the shuttle for engagement by the packages, mechanism for moving the banded packages away from the rear portion of the shuttle, mechanism for rendering the banding mechanism operative and inoperative relatively to the shuttle, and mechanism for moving the banded packages away from the rear portion of the shuttle and controlling by one direction of movement thereof the

feed of the bands to the rear portion of the shuttle.

97. In a cigarette packaging machine, mechanism for supplying and placing charges of cigarettes in inclosure means and completing said inclosure means relatively to the charges of cigarettes, a reciprocating shuttle into which the inclosed charges of cigarettes are successively delivered for further treatment and regularly discharged from the shuttle by engagement of the inclosed charges with one another, banding mechanism for feeding and cutting predetermined lengths of bands and disposing the bands across the rear portion of the shuttle for engagement by the packages, mechanism for moving the banded inclosed charges of cigarettes away from the rear portion of the shuttle and for discharging the said inclosed charges from the machine, and a conveying means carrying cups into which the banded inclosed charges of cigarettes are discharged.

98. In a cigarette packaging machine, mechanism for supplying and inclosing charges of cigarettes and forming packages, a reciprocating shuttle into which the packages are successively delivered for further treatment, the packages being expelled from the shuttle by the successive introduction of other packages thereinto, mechanism for disposing bands across the rear portion of the shuttle, the bands being applied to the packages by the movement of the latter thereagainst, conveying means carrying cups, and mechanism for discharging the banded packages successively into the cups.

99. In a cigarette packaging machine, mechanism for supplying and positioning charges of cigarettes and wrappers associated therewith for progressive treatment, the wrappers being formed of a material which will adhere when heated, mechanism for loosely completing the folds of the wrappers about the charges of cigarettes, a reciprocating shuttle into which the packages of cigarettes are delivered for further treatment, a discharge chute to receive the packages of cigarettes from the shuttle, the packages of cigarettes being expelled from the shuttle by the successive introduction of packages in the shuttle, and heating means associated with the chute for engaging portions of the wrappers to seal the latter.

In testimony whereof I have hereunto set my hand in presence of two subscribing witnesses.

EDWARD L. BRACY.
